VERTICAL WALL SUSPENDED COMPARTMENTS
Harold J. Dielman, Lyndhurst, Ohio, assignor to The
Sanymetal Products Company, Inc., Cleveland, Ohio, a
corporation of Ohio

Filed Jan. 6, 1964, Ser. No. 335,876
25 Claims. (Cl. 52—239)

This invention relates to vertical wall suspended compartments, and more particularly to cubicle assemblies such as toilet enclosing compartments, hospital compartments, utility room compartments and the like, which are entirely supported in cantilever suspension from a vertical interior wall of the building and without floor or ceiling support.

Increased sanitation of room installed compartments or cubicles, can be attained when the dividing partitions as well as the front wall-forming panels or pilasters and doors which form the cubicle sections, are positioned in spaced relation to both the room floor and ceiling, and which permits convenient mopping and cleaning of the room floor, as well as convenient cleaning of the vertical walls and ceiling of the room in which they are installed.

Vertical wall suspended compartments and cubicle assemblies are essentially composed of a series of one or more cubicle sections each comprising a dividing partition whose base end is secured in cantilever suspension from the vertical room wall, a transversely extending front wall forming panel or pilaster secured to the front end of the dividing partition, and a door hingedly mounted on a vertical jamb edge of the front wall forming panel or pilaster. As thus constructed, the door body is hingedly supported in cantilever suspension from the front wall-forming panel or pilaster, the pilaster and door combination are together supported in cantilever suspension from the dividing partition, and finally the door, front wall-forming pilaster and dividing partition itself, are all basically supported in cantilever suspension from the vertical room wall.

If such vertical wall suspended compartments or cubicles are to permanently withstand the rigors of use and abuse, serious structural, mounting, anchoring, leveling and aligning problems are presented. For example, the series of dividing partition-supported front wall panels or pilasters must be maintained in precise alignment, with the adjacent vertical jamb forming edges of the pilasters precisely spaced to define a door opening therebetween into which a prefabricated door may be precisely fitted, with one vertical edge of the door hingedly mounted on a vertical jamb edge of one of the pilasters, and with the opposite vertical edge of the mounted door positioned to abut against a door stop attached to the adjacent vertical edge of the adjacent pilaster or front wall forming panel.

For a permanent and lasting cubicle installation, the vertical base end of each dividing partition must be rigidly anchored in cantilever suspension from the vertical room wall in a manner to prevent both sidesway or downward sag of the dividing partition, since any sidesway or downsag thereof would throw the front wall-forming pilaster attached thereto out of precise alignment with the adjacent pilaster, and also dimensionally change the door opening defined between adjacent front wall-forming pilasters. Additionally, to attain precise alignment of adjacent front wall forming pilasters and precisely dimensioned door receiving openings therebetween, the vertical base end of each dividing partition must be precisely leveled so that the medial center lines of all dividing partitions are in precise parallelism.

Each vertical wall suspended dividing partition, used for example as components for toilet enclosing cubicles, should be in the order of four to five feet in height when

2

the lower end thereof is spaced a distance of approximately one foot from the floor, and should have a horizontal length of four to five feet or more. Because of the substantial horizontal length of the cantilever supported dividing partition, substantial leverage stresses are exerted thereon by reason of the weight of the pilaster and door suspended from the front end of the dividing partition, and the weight of the dividing partition itself. Accordingly, each dividing partition must be so constructed and reinforced that it will rigidly and permanently maintain its cantilever mounted position on the vertical room wall, and resist all downsag, sidesway, bending, warping, twisting and deformation stresses resulting from the inherent weight of the dividing partition itself, as well as the inherent weight of the door and pilaster as supported and suspended from the front end of the dividing partition. In addition, the dividing partition must be adequately strong and rigid to also resist all strains and stresses which may be externally imposed thereon through years of use and abuse.

It must be anticipated that particularly severe strains and stresses will be imposed on the vertical wall anchoring means, the dividing partition, and front wall-forming pilaster and door as supported thereby during long years of use of the installation, as a result of body weights and other substantial hanging loads applied to the upper end of the door, pilaster and/or dividing partition during use of the installation. Such externally applied forces impose severe sidesway and downsag stresses on the anchoring means, and impose severe downsag, sidesway, bending, warping, twisting, and other deformation stresses on the cantilever suspended dividing partition, as well as on the front wall forming pilaster attached thereto.

Vertical wall suspended compartment or cubicle assemblies constructed in accordance with this invention, are particularly designed to withstand and resist all conceivable downsag, sidesway, bending, warping, twisting and other deformation stresses which may be imposed thereon during a lifetime of use and abuse of the installation.

In accordance with this invention, each vertical wall suspended dividing partition contains a structural framework which includes a vertically extending base frame member which is preferably channel shaped in transverse section and presents a web portion of approximately five to six inches in transverse width, and a pair of opposite side flanges approximately three inches wide which have a slight forward taper. To further strengthen the dividing partition construction, a pair of arms each preferably generally channel shaped in transverse section, may be rigidly secured at one end thereof to the opposite upper and lower ends of the channel shaped base frame member, and which together form a rigid base frame of generally U-shaped form. The channel-shaped base frame member has a vertical length which substantially corresponds to the vertical height of the dividing partition at the base end thereof, and the channel-shaped arms may have a horizontal length of approximately one to two feet. The channel-shaped vertically extending base frame member and the channel-shaped horizontally extending arms are preferably shaped from strong metal plates of approximately one-eighth inch thickness.

The internal framework also includes a series of horizontally extending and vertically spaced reinforcing and bracing members of generally wedge-shaped form in horizontal length, and whose larger base ends extend into the channel-shaped base frame member and are preferably adhesively bonded to the inner surfaces of the web portion and the side flanges thereof. When horizontally extending upper and lower arms are also rigidly secured to the upper

and lower ends of the channel-shaped base frame member to provide an internal U-shaped base frame for the dividing partition, the base ends of the uppermost and lowermost horizontally extending and wedge-shaped bracing members are pocketed within the respective channel-shaped arms, and preferably also adhesively bonded to the inner faces of the web portion and side flanges of the respective horizontal arms of the U-shaped base frame. To reduce the weight of the dividing partition, without sacrifice of adequate stiffness and strength, the horizontally extending and wedge-shaped bracing members are each preferably composed of a plurality of layers of corrugated paperboard adhesively bonded together to provide a composite thickness of from one to three inches, and which composite member is also chemically treated to increase its stiffness and strength, increase its heat resistance capability, and prevent shrinkage thereof during extended use.

When the front wall forming panel or pilaster is prefabricated as a unit for attachment to the front end of the unitary dividing partition as by suitable brackets, the front end of the unitary dividing partition also contains an internal front frame member which is approximately one to two inches in thickness and to whose inner vertical face the front ends of the horizontally extending and wedge-shaped bracing members are adhesively bonded. The front frame member thus forms a part of the internal reinforcing framework of the dividing partition, provides a solid base to which the pilaster supporting brackets can be rigidly secured, and is preferably made of wood to further reduce the inherent weight of the dividing partition, with the wood front frame member preferably chemically treated to increase its resistance to heat and prevent shrinkage thereof in use.

Side wall forming panels, each shaped from a relatively light gauge metal or plastic sheet, are applied to the opposite sides of the internal framework of the dividing partition. Each side wall forming panel presents a vertically extending inturned flange which overlaps and is rigidly secured to the rear face of the vertically extending base frame member, and a side wall facing section which extends from the base end to the front end of the dividing partition. The upper and lower horizontal ends of each side wall facing section present inturned flanges which overlap the top and bottom faces of the uppermost and lowermost horizontally extending and wedge-shaped bracing members, with each of the upper and lower inturned flanges terminating in an outflared lip. A panel reinforcing liner is adhesively bonded to the inner face of the side wall-forming section of each side wall facing panel, and is in turn adhesively bonded to the adjacent side faces of the wedge-shaped bracing members. Each panel liner may be formed from a sheet of corrugated paperboard approximately one-eighth inch thick which has been chemically treated to increase its stiffness, heat resistance and resistance to shrinkage.

Upper and lower horizontally extending cap members of generally wedge-shaped form in horizontal length, are telescopically applied to the upper and lower ends of the paired side wall facing sections and extend from the rear base end to the front end of the dividing partition. Each horizontally extending hood or cap members presents inturned lips along the side edges thereof which interlock with the outflared lips extending from the upper and lower inturned flanges of the side wall facing sections.

The facing section of each wedge-shaped cap member may be generally V-shaped in transverse section to enhance the architectural appearance of the installation. Alternatively, each wedge-shaped cap member may present a relatively flat facing section. As a further alternative, the paired inturned flanges extending along the upper and lower ends of the side wall facing sections may each be generally wedge-shaped in horizontal length, with the inner edges thereof substantially in abutment along the medial center line of the dividing partition, and which

terminate in adjacent outflared lips which may be externally bonded together, and to which a cap member in the form of semi-tubular and horizontally extending edging strip may be telescopically applied. The paired wedge-shaped inturned flanges extending from the upper and lower ends of the paired side wall facing sections may extend in a substantially horizontal plane and normal to the paired side wall facing sections; or the paired wedge-shaped inturned flanges may be inclined at an angle with respect to the vertical plane of the side wall forming sections and which terminate in adjacent outflared lips which are externally bonded together and which extend horizontally along the medial center line of the dividing partition, and to which a semi-tubular cap member is telescopically applied.

Where the front wall forming panel or pilaster is fabricated as an independent unit for securement as by suitable brackets to the front end of the independently fabricated dividing partition unit, the front end of such unitary dividing partition is preferably of finished construction, and presents paired inturned flanges extending inwardly from the paired side wall facing sections and in overlapping relation to the front face of the internal front frame member of the unitary dividing partition. The complementary front inturned flanges terminate in adjacent outflared lips which are externally secured together to increase the strength of the dividing partition, and to which a vertically extending semi-tubular edging strip is telescopically interlocked. The upper and lower ends of the front semi-tubular edging strip are shaped to interfit with the front ends of the horizontal cap members, and the joints so formed are preferably welded together and burnished to provide finished upper and lower corners for the unitary dividing partition.

When the front wall forming panel or pilaster is prefabricated as a unit, it may be composed of complementary inner and outer facing pans having a longitudinal height substantially corresponding to the vertical height of the front end of the dividing partition to which it is to be applied, and has a transverse width of three to eight inches or more, as determined by the dimensional requirements of the door opening to be defined between the adjacent pilasters associated with each cubicle section of the installation. The complementary rear and front facing pans present complementary inturned edge-forming flanges along the vertical and horizontal edges thereof, which terminate in paired outflared lips to which corresponding vertical and horizontally extending semi-tubular edging strips are telescopically applied. During assembly of the pilaster body, a reinforcing plate is bonded to the inner face of the rear facing pan, a reinforcing core is bonded to the reinforcing plate and also bonded to the inner face of the front facing pan when the complementary rear and front facing pan are assembled together to form the pilaster body. The adjacently paired outflared lips extending along the vertical and horizontal edges of the pilaster body are externally secured together before the semi-tubular edging strips are applied thereto, to provide a strong and rigid pilaster construction. The unitary pilaster is rigidly mounted on the front end of the unitary dividing partition as by suitable brackets secured to the outer face of the rear facing pan and to the reinforcing plate contained therein, and also secured as by thru-bolts extending through the front ends of the paired side wall facing sections and the internal front frame member of the unitary dividing partition.

In another form of this invention, each cubicle section may be fabricated as an integral unit, with the front wall forming panel or pilaster fabricated as an integral part of the dividing partition part. In such construction, the internal framework of the dividing partition part may be similar in construction to the internal framework used in constructing a unitary dividing partition, except that no internal front frame member need be employed. The internal framework for the dividing partition part of the

composite dividing partition and pilaster unit, may comprise a vertically extending base frame member channel-shaped in transverse section, and with or without channel-shaped horizontally extending arms secured to the upper and lower ends thereof. A series of vertically spaced and horizontally extending wedge-shaped bracing members have the base ends thereof bonded to the inner faces of the web portion and side flanges of the vertically extending channel-shaped base frame member, and extend to the front end of the dividing partition part.

The paired side wall forming panels for this unitary dividing partition and pilaster construction together present paired inturned flanges along the rear vertical ends thereof which overlap and are rigidly secured to the rear face of the channel-shaped base frame member, and together present forwardly tapering side wall facing sections which form the side walls of the dividing partition part. The upper and lower ends of the paired side wall facing sections present paired inturned flanges which overlap the outer faces of the uppermost and lowermost wedge-shaped bracing members, and terminate in paired out-flared lips to which horizontally extending upper and lower cap members may be telescopically interlocked.

The front ends of the side wall facing sections of the unitary dividing partition and pilaster construction present laterally flared and transversely aligned flange sections which together form the rear wall of the pilaster part. A sound deadening and reinforcing core is bonded to the inner faces of the laterally extending flange sections, and to the adjacent front ends of the horizontally extending and wedge-shaped bracing members exposed therebetween. A front facing pan is applied and adhesively bonded to the pilaster reinforcing core, and presents inturned edge-forming flanges along the vertical and horizontal edges thereof which are complementary to corresponding inturned edge-forming flanges presented by the vertical and horizontal ends of the laterally extending flange sections which form the rear wall of the pilaster part. The complementary vertical and horizontally extending edge-forming flanges terminate in outwardly flared lips which are externally welded or bonded together to provide a strong pilaster part, and corresponding semi-tubular edging strips are telescopically applied and interlocked to the outflared lips.

Upper and lower horizontally extending cap members, each presenting inturned lips, are telescopically interlocked with the paired outflared lips extending along the upper and lower ends of the side wall-forming sections of the dividing partition part. The front ends of the upper and lower cap members are preferably coped to interfit with the horizontally extending semi-tubular edging strips applied to the adjacent horizontal ends of the pilaster body, and the joints as thus formed are preferably welded and burnished to provide finished joints.

Either one or both of the vertical jamb forming edges of the unitary pilaster, or the pilaster part of the unitary dividing partition and pilaster unit, may present one or more pre-formed seating and locking portions to which a door stop, hinge bracket, or like hardware element may be rigidly secured, and which further facilitates the telescopic application of the vertical and horizontal edging strips to the pilaster body.

Dividing partitions and front wall forming pilasters associated therewith, when constructed in accordance with this invention, are relatively light in weight, strong and rigid in construction, and will withstand the most severe downsnag, sideway, bending, warping, twisting and other deformation strains which may be imposed thereon by external forces during many years of use and abuse.

This invention further embraces means for rigidly anchoring the base end of each dividing partition to the vertical room wall in a manner to prevent downsnag or sidesway of the dividing partition. Means are additionally provided for precisely leveling the base end of each dividing partition of the cubicle installation, so that the

dividing partitions will laterally extend in exact parallelism when mounted on the vertical room wall, and which leveling means may be manipulated to apply bracing tension on the wall anchoring means to insure that the base end of each dividing partition is rigidly and immovably anchored to the vertical room wall.

Other objects and advantages of this invention will become apparent as the disclosure proceeds.

Although the characteristic features of this invention will be particularly pointed out in the claims, the invention itself, and the manner in which it may be made and used, may be better understood by referring to the following description taken in connection with the accompanying drawings forming a part thereof, and in which:

FIG. 1 is a perspective view of a cubicle assembly constructed in accordance with this invention as the same would appear when installed in an interior room and supported in cantilever suspension from the tile faced vertical wall thereof, and in spaced relation to the room floor and ceiling;

FIG. 2 is a horizontal section of the cubicle assembly as the same would appear when viewed along line 2—2 of FIG. 1, and showing means which may be used to level and rigidly anchor the base end of each dividing partition of the cubicle assembly in cantilever suspension from the tile faced vertical wall of the room;

FIG. 3 is a side view of one of the cubicle sections of the cubicle assembly as viewed along line 3—3 of FIG. 2, and showing the unitary dividing partition and the unitary front wall forming pilaster attached by brackets thereto, and which further illustrates the means which may be employed for rigidly anchoring the base end of the dividing partition in cantilever suspension from the vertical room wall;

FIG. 4 is a perspective view of the unitary dividing partition as rigidly mounted on the vertical room wall, with the front wall forming pilaster detached from the dividing partition;

FIG. 5 is a vertical section of the unitary dividing partition as the same would appear when viewed along line 5—5 of FIG. 3 and showing certain details of its construction;

FIG. 6 is a fragmentary perspective view of the unitary dividing partition in exploded relation to the vertical room wall and showing in further detail the means employed for leveling and rigidly anchoring the base end of the dividing partition to the vertical room wall, this view also showing certain components of the dividing partition partially assembled and other components in exploded relation;

FIG. 7 is a fragmentary perspective view showing certain components of the unitary dividing partition in assembled relation as viewed from the base end thereof, this view also showing the leveling and tensioning means as applied to the base end of the dividing partition, and a fragmentary perspective view of the vertical front edging strip of the dividing partition and the unitary front wall forming pilaster, in exploded relation to the dividing partition;

FIG. 8 is a fragmentary side elevational view of the unitary dividing partition and a vertical section of the vertical room wall, this view also showing further details of the means employed for leveling and rigidly anchoring the base end of the dividing partition to the vertical room wall;

FIG. 9 is a fragmentary horizontal section of the vertical room wall and associated means for rigidly anchoring the dividing partition in cantilever suspension to the vertical room wall, this view also showing further details of the base end of the dividing partition in exploded relation to the wall anchoring means, with the leveling means adjustably secured to the base end of the dividing partition;

FIG. 10 is an other fragmentary section of the base end of the dividing partition as anchored to and leveled

with respect to the vertical room wall and as the same would appear when viewed along line 10—10 of FIG. 8, this view also showing the wall filler strips in exploded relation to the base end of the dividing partition; and

FIG. 11 is a fragmentary horizontal section of the unitary dividing partition with its leveled base end rigidly anchored in cantilever suspension from the vertical room wall and with the removable wall filler strips applied thereto, this view also showing a horizontal section of the unitary front wall forming pilaster secured by brackets to the vertical front end of the unitary dividing partition.

FIG. 12 is an elevational view of a leveling and tension pad designed to be adjustably secured to the base end of the dividing partition and to brace against the frontal plate applied to the vertical room wall in the manner shown in FIGS. 8, 10 and 11; and

FIG. 12A is an elevational view, partly in section, of the leveling and tension pad shown in FIG. 12 and illustrating further details of its construction.

FIG. 13 is a perspective view of a U-shaped base frame made in accordance with this invention and which may be used to form a component part of the internal framework of the dividing partition, to further increase its rigidity and strength;

FIG. 14 is a fragmentary perspective view of a dividing partition constructed in accordance with this invention and which incorporates the U-shaped base frame shown in FIG. 13 as a part of its internal framework, this view also showing the front vertical edging strip and the upper and lower cap members in exploded relation to assembled components of the dividing partition, certain parts being shown in section to reveal structural details;

FIG. 15 is a perspective view of the unitary dividing partition shown in FIG. 14 as it would appear when fully assembled, certain parts being broken away to reveal structural details;

FIG. 15A is a fragmentary vertical section of this dividing partition as it would appear when viewed along line 15A—15A of FIG. 15; and

FIG. 15B is another fragmentary vertical section of this dividing partition as it appears when viewed along line 15B—15B of FIG. 15.

FIG. 16 is a perspective view of a unitary dividing partition made in accordance with this invention whose upper and lower cap members present relatively flat facing sections;

FIG. 17 is an elevational view of the base end of the unitary dividing partition shown in FIG. 16 as the same would appear when viewed along line 17—17 thereof;

FIG. 18 is a fragmentary perspective view of one of the front corners of the unitary dividing partition shown in FIG. 16 and showing the manner in which the front end of the relatively flat cap member of the dividing partition is interfitted and welded to the adjacent end of the front vertical edging strip thereof to provide a finished corner, certain parts being broken away to illustrate structural details thereof;

FIG. 19 is another perspective view of the dividing partition shown in FIG. 16 as the same would appear when viewed from the base end thereof, certain parts being broken away to illustrate structural details;

FIG. 20 is a vertical transverse section of this dividing partition as the same would appear when viewed along line 20—20 of FIG. 19;

FIG. 21 is another vertical section of this dividing partition as the same would appear when viewed along line 21—21 of FIG. 19; and

FIG. 22 is a further vertical section of this dividing partition as the same would appear when viewed along line 22—22 of FIG. 19.

FIG. 23 is a perspective view of a further modified form of a unitary dividing partition made in accordance with this invention, the side wall facing sections of the side wall-forming panels of the dividing partition presenting paired wedge-shaped flanges extending inwardly along the upper

and lower ends thereof, whose inner edges terminate in adjacently paired ouflared locking lips extending along the medial center line of the dividing partition, and to which a horizontally extending semi-circular edging strip is telescopically interlocked;

FIG. 24 is an elevational view of the base end of the dividing partition shown in FIG. 23 as the same would appear when viewed along line 24—24 of FIG. 23;

FIG. 25 is a fragmentary perspective view of one of the front corners of the unitary dividing partition shown in FIG. 23, and which illustrates in further detail the manner in which the front end of the horizontally extending semi-tubular cap member is fitted and welded to the adjacent end of the front vertical edging strip of the dividing partition, certain parts being broken away to illustrate structural details;

FIG. 26 is another perspective view of the dividing partition shown in FIG. 23 as viewed from the base end thereof, certain parts being broken away to reveal structural details;

FIG. 27 is a vertical transverse section of this dividing partition as the same would appear when viewed along line 27—27 of FIG. 26;

FIG. 28 is another vertical transverse section of this dividing partition as the same would appear when viewed along line 28—28 of FIG. 26; and

FIG. 29 is a further vertical transverse section of this dividing partition as the same would appear when viewed along lines 29—29 of FIG. 26.

FIG. 30 is a perspective view of a cubicle assembly constructed in accordance with this invention and composed of a series of cubicle sections each presenting a front wall-forming pilaster fabricated as an integral part of the dividing partition with which it is associated, this view showing the cubicle assembly as the same would appear when installed in an interior room and supported in cantilever suspension from the tile faced vertical wall thereof and in spaced relation to the floor and ceiling;

FIG. 31 is a horizontal section of the cubicle assembly shown in FIG. 30 as the same would appear when viewed along line 31—31 thereof, this view also showing means which may be used for leveling and rigidly anchoring the base ends of the dividing partitions in cantilever suspension to the tile faced vertical wall of the room;

FIG. 32 is a side view of this cubicle assembly as viewed along line 32—32 of FIG. 31, and which shows one of its dividing partitions and pilaster units whose base end is rigidly anchored in cantilever suspension from the vertical room wall;

FIG. 33 is a fragmentary elevation of the dividing partition and pilaster unit shown in FIG. 32 with certain parts broken away to reveal structural details, this view also showing a vertical section of the room wall and further details of the means employed for leveling and rigidly anchoring the base end of the dividing partition part to the vertical room wall;

FIG. 34 is a fragmentary horizontal section of the vertical room wall, the dividing partition and front wall-forming pilaster unit as the same would appear when viewed along line 34—34 of FIG. 33, this view also showing further details of the means employed for leveling and rigidly anchoring the base end of the dividing partition to the vertical room wall and modified wall filler strips in exploded relation to the dividing partition;

FIG. 35 is a fragmentary perspective view of a front corner of this dividing partition and pilaster unit which shows the manner in which the front end of the cap member as applied to the dividing partition part is coped into matching relation to the adjacent horizontal edging strip of the front wall-forming pilaster part;

FIG. 36 is an elevational view of the base end of the dividing partition part of the cubicle unit as the same would appear when viewed along line 36—36 of FIG. 33;

FIG. 37 is a vertical transverse section of the dividing

partition part as the same would appear when viewed along line 37—37 of FIG. 33;

FIG. 38 is an elevational view of the front wall-forming pilaster part of the dividing partition and pilaster unit shown in FIGS. 33, 34 and 35, the front wall-facing pan of the pilaster being partially broken away to reveal the internal reinforcing core and the rear wall-forming sections of the pilaster which are formed as an integral part of the facing panels of the dividing partition, and as the same would appear when viewed along line 38—38 of FIG. 33, this view also showing the upper hinge bracket and the lower hinge bracket made in accordance with this invention in exploded relation to bracket receiving seat formations formed on one vertical edge of the pilaster body, and a reversible door stop made in accordance with this invention in exploded relation to the door stop receiving seat formation formed on the other vertical edge of the pilaster body; and

FIG. 38A is an exploded elevational view of the rear wall-forming sections of the pilaster part which form an integral part of the side wall-facing panels of the dividing partition part, this view also showing the perimetrical edging strips of the pilaster in exploded relation to the rear wall-forming sections of the pilaster.

FIG. 39 is a fragmentary perspective view of the pilaster which shows the door stop receiving seat formation of the pilaster, and a reversible door stop in exploded relation thereto;

FIG. 40 is a fragmentary vertical section of the pilaster shown in FIG. 39 and a vertical section of the reversible door stop in process of application to the pilaster;

FIG. 40A is a transverse section of the pilaster and associated door stop applied thereto, as the same would appear when viewed along line 40A—40A of FIG. 40;

FIG. 40B is another transverse section of the pilaster and reversible door stop as finally locked to the pilaster, and as the same would appear when viewed along line 40B—40B of FIG. 40; and

FIG. 40C is another transverse section of the pilaster and reversible door stop applied thereto, and as the same would appear when viewed along line 40C—40C of FIG. 40.

FIG. 41 is a fragmentary perspective view of a further form of dividing partition and front wall forming pilaster unit constructed in accordance with this invention, and wherein the side wall-forming panels of the dividing partition present upper and lower wedge-shaped flange sections integral therewith and which are interlocked together by horizontally extending upper and lower semi-tubular cap members which extend along the medial center line of the dividing partition part, with the front end of the semi-tubular cap member coped into matching relation with the adjacent horizontal edging strip of the pilaster part, this view also showing wall filler strips of modified form applied to the base end of the dividing partition part.

FIG. 42 is a vertical section of the dividing partition part shown in FIG. 41 as the same would appear when viewed along line 42—42 thereof, this view also showing the wall filler strips in exploded relation to the base end of the dividing partition part;

FIG. 43 is an exploded perspective view of certain components of the dividing partition part of the cubicle unit shown in FIG. 41, some of the components being fragmentarily shown;

FIG. 44 is a top plan view of the modified dividing partition and pilaster unit shown in FIG. 41 in exploded relation to the vertical room wall, this view also showing leveling and tension pads adjustably attached to the base end of the dividing partition part, and means associated with a vertical room wall for rigidly anchoring the base end of the dividing partition part thereto;

FIG. 45 is an exploded plan view of certain components of the dividing partition and pilaster unit and wall filler

strips shown in FIGS. 41, 42 and 44, and which reveals further structural details thereof;

FIG. 46 is a fragmentary horizontal section of the dividing partition and pilaster unit as the same would appear when viewed along line 46—46 of FIG. 41; and

FIG. 47 is a fragmentary perspective view of a front corner of the dividing partition part and the adjacent end of the front wall-forming pilaster part of the cubicle unit shown in FIGS. 41 and 44, this view illustrating the manner in which the front end of the horizontally extending semi-tubular cap member of the dividing partition part is coped and matched to the adjacent horizontal edging strip of the pilaster part.

FIG. 48 is an elevational view of a modified form of leveling and tension applying pad which is also shown adjustably applied to the base frame member of the dividing partition as shown in FIGS. 44, 45 and 46, and which insures rigid attachment of the base end of the dividing partition to the vertical room wall; and

FIG. 48A is another elevational view, partly in section, of the leveling and tension pad shown in FIG. 48, and which reveals further details of the construction thereof.

FIG. 49 is a vertical section of a two-sectioned building wall of masonry construction as customarily spaced apart to provide interior space for service piping, and wherein one section of the wall is tiled to provide the interior wall of the room in which the cubicle assembly is installed, this view showing modified anchoring elements installed during erection of the interior room wall and to which the base end of the dividing partition may be anchored, this view also showing the base end of the dividing partition and associated means for leveling and rigidly anchoring the base end of the dividing partition to the vertical room wall;

FIG. 49A is a horizontal section of the construction shown in FIG. 49 as viewed along line 49A—49A thereof; and

FIG. 49B is a horizontal section of the construction shown in FIG. 49 as viewed along lines 49B—49B thereof.

FIG. 50 is a vertical section of a two sectioned building wall having wing anchors which may be applied to the interior room wall section after the twin sectioned building wall has been erected, this view also showing the leveling and tensioning means applied to the base end of the dividing partition and the means for rigidly securing the base end of the dividing partition in cantilever suspension to the wing anchors;

FIG. 50A is a fragmentary transverse section of the construction shown in FIG. 50 as the same would appear when viewed along line 50A—50A thereof; and

FIG. 50B illustrates the manner in which the wing anchors may be applied to the previously erected vertical room wall.

FIG. 51 is a vertical section of a twin-sectioned building wall which shows modified anchoring elements which may be applied to the interior room wall section after erection thereof, this view also showing leveling and tensioning means applied to the base end of the dividing partition and means for rigidly securing the base end of the dividing partition to these anchoring elements; and

FIG. 51A is a transverse section of the construction shown in FIG. 51 as the same would appear when viewed along line 51A—51A of FIG. 51.

Similar reference characters refer to similar parts throughout the several views of the drawings and the specification.

Vertical wall suspended compartments or cubicles constructed in accordance with this invention as shown in FIGS. 1 and 2, are composed of one or more cubicle sections each comprising a separately fabricated dividing partition unit S which is generally wedge-shaped in horizontal section, and a separately fabricated front wall-forming pilaster P which is attached to the front end of the dividing partition as by brackets 15. Each dividing partition unit S and pilaster unit P may be constructed as

shown in FIGS. 3-11, or FIGS. 13-15, or FIGS. 16-22, or FIGS. 23-29. The vertical base end of each dividing partition unit is rigidly secured to the inner vertical wall V of the room in which the cubicle sections are installed, as by anchoring means A as shown in FIGS. 1-11, or anchoring means A' as shown in FIGS. 49-49B, or anchoring means A'' as shown in FIGS. 50-50B, or anchoring means A''' as shown in FIGS. 51 and 51A. The anchoring means A and A' are designed to be embedded in the interior vertical room wall during construction thereof, while the anchoring means A'' and A''' may be embedded in the interior vertical room wall after construction thereof.

These anchoring means are designed to rigidly secure the base end of each dividing partition in spaced relation to the tile facing Vt of the vertical room wall V; and cooperating with leveling and tension applying pads T formed as shown in FIGS. 12 and 12A, or leveling and tension applying pads T' formed as shown in FIGS. 48 and 48A, which are adjustable after application to the base end of the dividing partition, to insure that the medial center line of respective dividing partitions of the cubical units are in precise parallelism and so maintained during use and abuse of the installation.

After the dividing partition of each cubicle unit has been leveled and rigidly anchored to the vertical room wall to support the cubicle unit in cantilever suspension, the space defined between the vertical room wall and the base end of each dividing partition and which permits external manipulation and adjustment of the anchoring means and leveling and tension applying pads, is concealed by removable wall filler strips F which extend around the base end of the dividing partition, and snugly abut the tiled face of the vertical room wall.

When the dividing partitions S are constructed as more fully hereafter described, and when the base ends thereof are properly leveled and anchored to the vertical room as hereafter described, a precisely dimensioned door opening is defined between adjacent pilasters as mounted on the front ends of the vertical wall suspended dividing partitions, and in which a prefabricated door D may be positioned and swingably hinged to the vertical edge of the adjacent pilaster.

The vertical wall suspended dividing partition unit S as shown in FIGS. 3-11, has an internal framework composed of a vertical base frame member 1 formed of a metal plate approximately one-eighth inch thick, and whose vertical length substantially corresponds to the vertical height of the dividing partition. The base frame member 1 is preferably channel shaped in transverse section, and presents a web portion 1' which is approximately five to six inches in transverse width, and side flanges 1'' approximately three inches wide and having a slight forward taper to accord with the wedge-shaped form of the partition itself. The internal framework also includes a vertical front frame member 3 which has a vertical length substantially corresponding to the vertical length of the channel-shaped base frame member 1, and a transverse width or thickness in the order of one to two inches. The vertical front frame member 3 as shown in FIG. 6 is made of treated hardwood, but can be made of metal or plastic in the form of a three-sided channel or rectangular tube.

A series of horizontally extending bracing members 5 of generally wedge-shaped form in horizontal length, extend between and may be adhesively bonded to the inner face of the web portion 1' and tapered side flanges 1'' of the channel-shaped base frame member 1 and to the inner face of the vertical front frame member 3. The wedge-shaped bracing members 5 may be made of wood or metal, but as shown in FIGS. 5 and 6 are preferably composed of a series of corrugated paperboard layers bonded together by bonding adhesive and chemically treated for additional stiffness and heat resistance and to prevent shrinkage in use. In the framework construction shown

in FIGS. 5 and 6, seven wedge-shaped bracing members 5 are employed, each having a thickness of one to three inches. The uppermost and lowermost wedge-shaped bracing members 5 are positioned adjacent the upper and lower ends of the vertical base frame member 1 and the front vertical frame member 3, with the next adjacent wedge-shaped reinforcing members 5 positioned approximately six inches therefrom. The remaining intermediate wedge-shaped bracing members 5 are spaced approximately one foot apart.

The side walls of the wedge-shaped dividing partition shown in FIGS. 3-11 are formed by a pair of side wall forming panels 2-2 each formed from metal or plastic sheeting of approximately 20 gauge thickness, and each panel 2 presents a flat side wall facing section 2a having an inturned rear vertical flange 2b as shown in FIG. 7 which overlaps the rear face of the web portion 1' of the channel-shaped vertical base frame member 1 and is welded or otherwise rigidly bonded thereto. The front vertical end of each side wall facing section 2a presents an inturned front flange 2e which snugly overlaps the flat front face of the vertical front frame member 3 and terminates in an outflared front lip 2f. When the complementary side wall facing panels 2-2 are assembled to the internal framework the adjacent outflared front lips 2f-2f thereof are secured together by welds or bonding adhesive w externally applied to the crotch defined between the adjacent outflared front lips 2f-2f.

As shown in FIGS. 5, 6 and 7, each side wall forming panel 2 also presents an inturned flange 2c extending along the upper and the lower horizontal edges thereof which snugly overlap the adjacent upper and lower ends of the adjacent side flange 1'' of the channel-shaped base frame member 1 and the upper and lower ends of the vertical front frame member 3. The paired inturned flanges 2c-2c also snugly overlap and may be adhesively bonded to the outside faces of the adjacent uppermost and lowermost horizontally extending wedge-shaped reinforcing members 5-5. As shown in FIGS. 5, 6, and 7, each horizontally extending inturned flange 2c has a transverse width of approximately one-half inch to one inch, and terminates in an outflared lip 2d.

A panel reinforcing liner 4 is adhesively bonded to the inner face of each side wall facing section 2a and extends between the vertical terminal edge of the adjacent side flange 1'' of the channel-shaped base frame member 1 and the adjacent inner face of the vertical front frame member 3. Each panel reinforcing liner 4 has a height substantially corresponding to the vertical height of the base frame member 1 and front frame member 3. Each panel liner 4 is preferably made of relatively light but strong and rigid material such as chemically treated plywood, composition board or corrugated paperboard as shown in FIG. 6, and has a thickness of approximately one-eighth inch or a thickness which substantially corresponds to the thickness of the side flanges 1'' of the relatively heavy gauge channel-shaped base frame member 1. The side edges of all the horizontally extending wedge-shaped bracing members 5 are adhesively bonded to the inner faces of the adjacent panel liners 4.

Upper and lower horizontally extending cap members 6, which are wedge-shaped in horizontal length and extend from the web portion 1' of the channel-shaped base frame member 1 to the front face of the vertical front frame member 3, may be formed of a relatively light gauge metal or plastic sheet. The upper and lower horizontally extending cap members 6 as shown in FIGS. 5 and 6, are generally V-shaped in transverse section and present tapered side sections 6b forming a crowned ridge along the medial center line of the dividing partition, and a pair of inturned lips 6a-6a along the side edges thereof which telescopically interlock with the paired and horizontally extending outflared lips 2d-2d extending along the upper and lower horizontal ends of the side wall facing sections 2a-2a.

A semi-tubular front edging strip 7, presenting a curvilinear facing section 7a and paired inturned locking lips 7b, is vertically telescoped over the inturned front vertical flanges 2e—2e of the side wall forming panels 2—2, with the outflared locking lips 7b—7b of the edging strip interlocked to the adjacent outflared lips 2f—2f of the side wall forming panels 2—2. The front ends of each of the upper and lower cap members 6 are mitre cut to interfit with the adjacent mitred ends of the front semi-tubular edging strip 7, and the corners as thus formed are then welded and burnished to provide finished upper and lower front corners 7c for the dividing partition unit, as shown in FIG. 4.

As shown in FIGS. 6—11, each side wall-facing section 2a has a series of vertically spaced and rectangular shaped holes 48' formed therein adjacent the rear vertical edge thereof, with correspondingly shaped rectangular holes 48' formed in the adjacent tapered side flange 1" of the channel-shaped base frame member 1 in alignment therewith, and which provide access openings through which a manipulating tool may be inserted for purposes hereafter described. The web portion 1' of the channel-shaped base frame member 1 has a series of spaced slot holes 45' through which wall anchored bolts or studs project, and also a series of spaced and threaded holes 35' for attachment to leveling devices T or T' as hereafter described, and which cooperate to level and rigidly anchor the base end of the dividing partition to the vertical room wall V as hereafter described. One of the side wall panels as shown in FIG. 6 may have a rectangular cut-out 49' formed therein, with a corresponding aligned hole formed in the panel liner 4 secured thereto. A receptacle such as a paper roll holder 49 as shown in FIG. 3 may be inset into the cut-out 49', when the dividing partition is to form a component part of a toilet cubicle.

The vertical wall suspended dividing partition as shown in FIGS. 3—11 can be constructed and fully assembled as a unit at the manufacturing plant by high speed production methods at relatively low cost. For example, the channel-shaped base frame member 1 may be blanked out from a heavy gauge metal plate on a die press, and in which operation the rectangular shaped holes 48' are cut in the side flange portions 1" thereof, and at the same time appropriately spaced holes 45' and 35' are punched from the web portion 1' thereof as shown in FIGS. 5 and 7, for attachment of the wall anchoring means A, A', A" or A''' and the leveling and tensioning pads T or T' as hereafter more fully described. The punched and shaped blank may then be accurately shaped into channel form on a press. The front vertical frame member 3, presenting slightly tapered side faces, is then cut to a length which corresponds to the length of the channel shaped base frame member 1. The wedge-shaped reinforcing members 5 may be cut from planks composed of a plurality of layers of chemically treated corrugated paper-board adhesively bonded together to provide a plank thickness in the order of one to three inches. Metal or plastic sheets of generally rectangular form are cut to appropriate size to provide the side wall panels 2—2, which are then shaped in a press so that each panel provides a side wall facing section 2a, an inturned rear vertical flange 2b, an inturned front vertical flange 2e and associated outflared front lip 2f, and inturned upper and lower flanges 2c each terminating in an outflared lip 2d. A panel liner 4, in the order of approximately one-eighth inch in thickness, is then adhesively bonded to the inner face of each side wall facing section 2a. The upper and lower cap members 6 may be blanked out into wedge-shaped form from a metal or plastic sheet, the blank then press formed to present tapered side sections 6b—6b and inturned lips 6a—6a along the longitudinal edges thereof.

In assembling the dividing partition as shown in FIGS. 3—11, the inturned rear vertical flange 2b of one of the side wall forming panels 2 is welded or bonded to the rear face of the web portion 1' of the channel-shaped

base frame member 1. The front vertical frame member 3 is inserted, with its front vertical face in abutment against the inner face of the inturned front flange 2e. The horizontally extending wedge shaped reinforcing members 5 are inserted with the base ends thereof adhesively bonded to the inner faces of the web portion 1' and side flanges 1" of the channel-shaped base frame member 1, the front ends thereof adhesively bonded to the inner face of the front vertical frame member 3, and the adjacent side edges 5 of each wedge shaped reinforcing member 5 adhesively bonded to the inner face of the panel liner 4 previously applied to the side wall facing panel 2. Horizontally extending strips of adhesive may then be applied to the opposite side edges of the horizontally extending wedge-shaped reinforcing members 5, or to the panel liner 4 bonded to the side wall facing section 2a of the companion side wall forming panel 2, and the companion panel then applied to the assembly, with its inturned rear vertical flange 2b positioned in overlapped relation and welded 10 or bonded to the outer face of the web portion 1' of the channel-shaped base frame member 1, and with its front vertical flange 2e snugly overlapping and bonded to the front vertical face of the front vertical frame member 3. The side wall facing sections 2a—2a of the paired side 15 wall-forming panels 2—2 as thus applied may then be pressed together to assure firm adhesive bond between the panel liners 4—4 and the tapered side edges of the wedge-shaped reinforcing members 5. The front semi-tubular edging strip 7 is then telescopedically applied to the 20 front inturned flanges 2e—2e of the side wall-forming panels 2—2, with the inturned lips 7b—7b of the semi-tubular edging strip 7 interlocked to the adjacent outflared lip portions 2f—2f of the side wall panels 2—2.

The upper and lower cap members 6—6 are then horizontally telescoped over the upper and lower ends of the side wall facing sections 2a—2a, with the paired inturned lips 6a—6a thereof interlocked to the paired outflared lips 2d—2d of the panel sections 2a—2a. The upper and lower mitre cut ends of the front edging strip 7 are 35 brought into mitre match with the coped front ends of the upper and lower cap members 6, and a seam weld is then applied to the upper and lower corner joints as thus formed to provide finished upper and lower front corners 7c for the dividing partition as shown in FIG. 4.

Each front-wall forming panel or pilaster unit P for the vertical wall suspended cubicle as shown in FIGS. 1—4, has a vertical height substantially corresponding to the vertical height of the dividing partition S and has a transverse width in the order of three to ten inches or 40 more, and of such width that adjacent aligned pilasters which form parts of the mounted cubicle assembly provide therebetween an accurately sized door opening in which the prefabricated door D is positioned. Each of the panels or pilaster units P is composed of a pair of complementary outer and inner facing pans 10—10', each 45 shaped in a press from a rectangular blank of relatively light gauge metal or plastic sheet, to provide a rectangular wall facing section 10a having inturned edge forming flanges 10b along both vertical and horizontal edges 50 thereof, with each edge forming flange 10b terminating in an outflared lip 10c.

A bracing plate 11 is welded along the perimeter thereof to the inside surface of the facing section 10a of the rear facing pan 10' to provide solid securement for the 55 saddle brackets 15 which secure the pilaster unit P to the front vertical edge of the dividing partition unit S as shown in FIGS. 4 and 11. A core 12 of sound deadening and reinforcing material, such as a corrugated paper-board or fibreglass slab, may be fitted within the rear facing pan 10' and adhesively bonded to the bracing plate 11 and the exposed inner face portions of the rear facing pan 10'. The outer face of the core 12 is then coated with adhesive to bond the core to the inner surface of the outer facing pan 10 as applied thereto. The complementary 60 outer and inner pans 10—10' present their inturned edge 70

75 outer and inner pans 10—10' present their inturned edge

forming flanges 10b substantially in alignment, with the paired outflared lips 10c—10c thereof substantially in abutment, and which can then be rigidly secured together by welds or adhesive externally applied to the crotch defined between the paired outflared lips 10c—10c.

The front wall-forming panel or pilaster unit P is completed by the application of semi-tubular edging strips 13 to the vertical and horizontal edges thereof. Each edging strip 13 presents a curvilinear facing portion 13' and paired inturned locking lips 13", as shown more particularly in FIG. 11, which respectively interlock with the paired outflared lips 10c—10c presented by the outer and inner facing pans 10—10'. The adjacent corner forming ends 13" of the vertically and horizontally extending semi-tubular edging strips 13 are preferably mitre cut to form interfitting corner joints which are seam welded together and then sanded to provide finished corners for the front panel or pilaster unit P. The front panel or pilaster unit P as thus constructed has a thickness in the order of one and one-half inches.

The front wall-forming panel or pilaster unit P is secured to the vertical front end of the dividing partition unit S either before or after the dividing partition S has been mounted on the vertical room wall V in the manner hereafter described. A pair of saddle shaped brackets 15, formed as shown in FIGS. 4 and 11, each present a pair of spaced saddle forming arms 15a—15a which telescope over the front vertical edge of the dividing partition and secured thereto by two or more clamp screws 16, each of which extend through a hole formed in one of the saddle forming arms 15a and into a bored hole formed in the side wall-forming facing section 2a and the vertical front frame member 3. An internally threaded cap nut 16a is inserted through a bored hole formed in the companion saddle forming arm 15a and is threadably secured to the threaded shank of each clamp screw 16. Each saddle bracket 15 also has a laterally extending arm section 15b preferably extending laterally from both sides of the saddle bracket. The laterally extending arm sections 15b present a flat front face designed to seat flatly against the outer surface of the facing section 10a of the rear facing pan 10', and is provided with bored holes through which securing screws 17 may be inserted and threadably secured to the inner bracing plate 11, as shown in FIG. 11.

As shown in FIGS. 1 and 2, each cubicle section of the cubicle assembly as mounted in cantilever suspension from the vertical room wall V comprises a dividing partition unit S of generally wedge-shaped form in horizontal plan and a wall-forming panel or pilaster unit P rigidly secured to the front end thereof as by spaced saddle brackets 15. A door D is swingably mounted as by upper and lower hinge brackets 21 and 23 to a vertical jamb edge of the pilaster P. A door stop 24 having a latchbolt receiving hole may be mounted on the opposite vertical edge of the pilaster, and which receives a retractable drawbolt associated with a door latch concealed within the door body and operatively connected to escutcheon medallions 33 exposed for hand manipulation on the outer surfaces of the door body.

To maintain the door receiving opening between adjacent spaced pilaster units P exactly dimensioned to snugly receive the swinging door D therebetween, it is apparent that the base end of the dividing partition units S must not only be rigidly anchored to the vertical room wall, as by anchoring means A, A', A'' or A''' forming a part of this invention and hereafter described, but the front wall-forming panels or pilaster units P of the respective cubicle sections must be vertically plumb and in precise alignment. This further requires that each dividing partition S should be of such rigid construction as to resist sidesway when lateral forces are applied thereto; and to additionally resist all downsag, bending, buckling, twisting and deformation forces resulting from the weight of the dividing partition S and the wall-forming pilaster P and swinging door D supported thereby, and to additionally

withstand years of use and abuse, such as substantial weights applied to the door or pilaster or dividing partition which may impose extreme downsag, sidesway, bending, buckling, twisting or deformation strains on the dividing partition.

While the dividing partition unit S constructed as shown in FIGS. 3-11, is relatively light in weight and can be manufactured at relatively low cost, it is nevertheless sufficiently and adequately rigid in construction to resist all sidesway, bending, twisting and deformation forces imposed thereon as a result of the weight of the cubicle section of which the dividing partition forms a component part, as well as external forces normally applied to any part of the cubicle section during many years of use and abuse. The great rigidity of the dividing partition S is attributable to its structural features, such as the internal framework comprising the heavy gauge channel-shaped base frame member 1 and the stiff and rigid horizontally extending wedge-shaped bracing members 5 whose rear and front ends are respectively bonded to the channel-shaped rear frame member 1 and the front frame member 3.

While the side panels 2—2 are of relatively light gauge, they also resist deformation stresses because the inturned rear vertical flanges 2b—2b thereof are welded or bonded to the rear face of the web section 1 of the base frame member 1; because their front vertical flanges 2e—2e terminate in adjacent outflared lips 2f—2f which are welded or bonded together by welds or bonding adhesive externally applied to the crotch between the adjacent outflared lips and then further reinforced by the semi-tubular edging strip 7 telescoped over and interlocked to the vertically extending outflared lips 2f—2f; and because the upper and lower horizontal ends of the side panels 2—2 present inturned horizontally extending flanges 2c—2c terminating in outflared lips locked together by the upper and lower cap members 6—6. The side wall panels 2—2 are further stiffened and reinforced against deformation by the panel liners 4—4 bonded to the inner surfaces of the side wall-forming sections 2a—2a thereof and to the side faces of the horizontally extending wedge-shaped bracing members 5. While the dividing partition as thus constructed has the advantage of being relatively light in weight and economical to manufacture, extensive tests have proven that it will not only support the weight of the pilaster P and door D, but will withstand normally encountered externally applied stresses without downsag, sidesway, bending, buckling, twisting or deformation, when its base end is securely anchored to a vertical room wall as hereafter described.

To further strengthen the dividing partition against high downsag, sidesway, bending, buckling, twisting, bending or other strains which may result from unusually heavy weights and forces externally applied to the dividing partition S, or applied to front wall-forming panel or pilaster P and door D supported thereby, the dividing partition as shown in FIGS. 5-11 may be further reinforced by incorporating a U-shaped base frame as a part of its internal framework.

As shown in FIGS. 13-15A, upper and lower arms 9—9, channel-shaped in transverse section, are rigidly secured to the upper and lower ends of the vertically extending channel-shaped base frame member 1, which may be formed in the same manner as the channel-shaped base frame member 1 illustrated in FIGS. 5-11 and previously described. Each horizontally extending channel-shaped arm 9 presents a web portion 9', which may be made approximately one to two feet long, and whose inner end is snugly fitted within the vertical channel-shaped base frame member 1 adjacent the end thereof, and rigidly secured as by welds w to the web portion 1' and tapered side flange sections 1" of the vertical base frame member 1. The horizontally extending side flanges 9" of each channel-shaped arm 9 have a forward taper

corresponding in degree to the horizontal wedge-shaped form of the dividing partition of which it forms a part. The rear ends of the side flanges 9" of each channel-shaped arm 9 are shaped to snugly abut the adjacent front edges of the respective side flange sections 1" of the base frame member 1, and are rigidly secured thereto as by welds w. The U-shaped base frame member, as thus constructed from heavy gauge channels, serves to strengthen and reinforce the dividing partition S against the most intense deformation strains.

In assembling the dividing partition S as shown in FIGS. 13-15B, the uppermost and lowermost wedge-shaped reinforcing members 5 are snugly fitted into the respective upper and lower channel-shaped arms 9-9 and adhesively bonded to the inner surfaces of the web portion 9' and side flanges 9" thereof, as shown in FIG. 14. The base end of all the vertically spaced and horizontally extending wedge-shaped reinforcing members 5 are also adhesively bonded to the inner surfaces of the web portion 1' and tapered side flanges 1" of the vertically extending channel-shaped base frame member 1 and the front ends of all wedge-shaped reinforcing members 5 are also adhesively bonded to the rear face of the vertical front frame member 3. Panel reinforcing liners 4-4, of approximately the same thickness as the side flanges 1" of the vertical base frame member 1 and the side flanges 9" of the horizontal arms 9-9, are cut and shaped to snugly interfit within the framework defined by the free vertical and horizontal perimetal edges of the side flanges 1" and 9" of the U-shaped base frame and the inner vertical edges of the vertical front frame member 3. As thus formed, the panel liners 4 snugly overlap the exposed side surfaces of the horizontally extending wedge-shaped reinforcing members 5 and are adhesively bonded thereto. As thus formed and applied, the relatively stiff and strong panel liners 4-4, and the horizontally extending wedge-shaped members 5, additionally reinforce the dividing partition and increase its resistance to deformation strains.

The panel liners 4-4 are adhesively bonded to the respective side wall-facing sections 2a-2a of the side wall-forming panels 2-2, and the exposed inner surface portions of the side wall-facing sections 2a-2a snugly overlap and may also be adhesively bonded directly to the exposed outer surfaces of the adjacent side flanges 1" and 9" of the U-shaped base frame and to the tapered side faces of the vertical front frame member 3. The in-turned flanges 2c-2c extending along the upper and lower horizontal edges of the side wall-forming panels 2-2 snugly overlap the web portions 9' of horizontally extending arms 9 and the upper and lower ends of the channel-shaped base frame member 1 and front frame member 3, and if desired, may be welded or otherwise rigidly secured thereto.

As shown in FIGS. 14 and 15, the uppermost and lowermost wedge-shaped bracing members 5-5, whose inner base ends are pocketed within the channel-shaped horizontally extending arms 9-9 of the base frame, each presents an exposed section 5' extending between the terminal end of the channel-shaped horizontal arm 9 and the front vertical frame member 3. To provide a snug seat for the full length of the in-turned flanges 2c-2c extending from the upper and lower ends of the side wall-facing sections 2a-2a, the exposed sections 5'-5' of the uppermost and lowermost wedge-shaped arms 5-5 may be thickened so that the outer upper and lower faces of these exposed sections form a substantially flush continuation of the outer face of the adjacent web portion 9' of the horizontal arm 9.

As shown in FIGS. 14, 15, 15A and 15B, the horizontally extending upper and lower in-turned flanges 2c-2c of the side wall-forming panels 2-2 may have a uniform width in the order of one-half to one inch, and terminate in outflared lips 2d-2d. Horizontally extending upper and lower hood caps or cap members 6-6 gen-

erally wedge-shaped in horizontal length and V-shaped in transverse section, are each provided with a pair of in-turned lips 6a-6a along the side edges thereof which interlock with the paired outflared lips 2d-2d of the side wall forming panels 2-2, when the cap members 6-6 are telescopically applied to the in-turned flanges 2c-2c extending horizontally along the upper and lower ends of the side wall-forming panels 2-2.

Each of the side wall forming panels 2-2 also presents a vertically extending in-turned base flange 2b which snugly overlaps and is welded or otherwise rigidly secured to the rear face of the web portion 1' of the vertical base frame member 1, and also presents a vertically extending in-turned front flange 2e which snugly overlaps and may be adhesively bonded to the front face of the vertical front frame member 3. The paired front in-turned flanges 2e-2e terminate in adjacently paired outflared lips 2f-2f secured together as by welds of bonding adhesive exteriorly applied to the crotch defined between the paired outflared lips 2f-2f, to further strengthen the construction. A front edging strip 7, presents a curvilinear outer face 7a and paired in-turned portions 7b which interlock with the paired outflared lips 2d-2d when the front edging strip is telescopically applied thereto. The upper and lower ends of the front edging strip 7 are coped to interfit with the front terminal ends of the upper and lower cap members 6-6 and the interfitted ends then welded together and burnished to provide smooth and finished front corners 7c for the dividing partition.

Means are provided, as hereafter described, for leveling and rigidly securing the base end of the dividing partition constructed as shown in FIGS. 14 and 15 to a vertical room wall. A front wall-forming panel or pilaster P, constructed as shown in FIGS. 4, 7 and 11 and heretofore described, is secured to the front end of this dividing partition as by spaced saddle brackets 15, and a door D may then be hingedly mounted on a jamb edge of the pilaster.

FIGS. 16-22 illustrate a dividing partition unit S whose base end is designed to be secured in cantilever suspension from a vertical room wall, and whose internal framework and other features of construction may be similar to the dividing partition shown in FIGS. 3-11 or FIGS. 14-15B, with the exception that its upper and lower horizontally extending cap members 6'-6' are relatively flat in transverse section rather than V-shaped in transverse section. Each cap member 6' presents a relatively flat facing section 6c which is generally wedge-shaped in horizontal length, and in-turned lips 6a-6a extending along the side edges thereof which interlock with the paired outflared lips 2d-2d extending from the paired in-turned flanges 2c-2c presented by the upper and lower ends of the side wall-forming panels 2-2. As shown in FIGS. 16 and 18, the front ends of the facing sections 6c-6c of the flat cap members 6'-6' overlap the square cut ends of the front semi-tubular edging strip 7, and the adjacent ends then welded together to form integral and finished upper and lower corners 7d of the dividing partition. The dividing partition as shown in FIGS. 16-22 may otherwise be made similar in construction to the dividing partition illustrated in FIGS. 3-11 or FIGS. 13-15B, and therefore is not further described.

As a further alternative, the vertical wall suspended dividing partition S may be constructed as illustrated in FIGS. 23-29, and wherein the upper and lower ends of the paired side wall-forming panels 2-2 thereof present upper and lower in-turned flanges 2c'-2c' of generally wedge-shaped form. When these side wall facing panels are assembled together with the internal framing components to form the assembled dividing partition, the paired wedge-shaped flanges 2c'-2c' are substantially in abutment along the medial centerline of the wedge-shaped partition, and terminate in adjacently paired outflared lips 2d-2d which are secured together by welds or bonds externally applied in the crotch defined between

the adjacent outwardly flared lips $2d-2d$. A cap member $6''$, in the form of a semi-tubular edging strip presenting a curvilinear outer face $6d$ and inturned locking lips $6a$, is telescopically applied to each pair of upper and lower wedge-shaped flanges $2c-2c'$, with the inturned lips $6a$ of the semi-tubular cap member $6''$ interlocking with the paired outflared lips $2d-2d$ extending horizontally along the medial centerline of the dividing partition. The front ends of the semi-tubular cap members $6''-6''$ are mitre cut to interfit with the adjacent mitre cut ends of the vertically extending front semi-tubular edging strip 7, and the corner joints as thus formed are welded and burnished to provide finished upper and lower front corners $7e$ of the dividing partition, as shown in FIGS. 23 and 25.

The modified dividing partition S illustrated in FIGS. 23-29 may otherwise be formed and constructed similar to the dividing partition S shown in FIGS. 3-11 or FIGS. 13-15B or FIGS. 16-22, and therefore will not be further described.

FIGS. 30-32 illustrate a vertical wall supported cubicle assembly in which each cubicle section comprises a dividing partition part S' and a front wall-forming panel or pilaster part P' which together provide an integrated dividing partition and pilaster unit.

As shown more particularly in FIGS. 31-38, the internal framework for the dividing partition part S' comprises a vertically extending base frame member 1 generally channel-shaped in transverse section and presenting a web portion 1' approximately five to six inches in transverse width, and forwardly tapering side flanges 1" approximately three inches wide. A series of vertically spaced and horizontally extending wedge-shaped reinforcing members 5 as shown in FIGS. 33 and 34 extend from the inner face of the web section 1' of the channel-shaped base frame member 1 to the front end of the dividing partition part.

Each horizontally extending reinforcing member 5 is preferably in the order of one to three inches thick and may be composed of a series of layers of corrugated paperboard adhesively bonded together and chemically treated to enhance its stiffness and resistance to heat and shrinkage. The base end of each wedge-shaped reinforcing member 5 is adhesively bonded to the inner faces of the web portion 1' and the forwardly tapered side flanges 1" of the channel-shaped base frame member 1.

In the construction shown in FIGS. 31-38, a pair of complementary side wall-forming panels 2'-2', formed of relatively light gauge metal or plastic sheet, are shaped to provide the side wall-facing sections 2a-2a of the dividing partition part S', and rear wall-forming sections 10" of the associated pilaster part P'. Each side wall-forming panel 2' has a side wall-facing section 2a which presents an inturned vertically extending flange 2b which overlaps the rear face of the web section 1' of the channel-shaped base frame member 1 and is welded or otherwise rigidly secured thereto. The upper and lower horizontal ends of each side wall-facing section 2a presents an inturned horizontally extending flange 2c approximately one-half to one inch in transverse width, and which extends from the adjacent end of the web section 1' of the base frame member 1 to the front end of the dividing partition forming part P' of the construction. Each horizontally extending inturned flange 2c snugly overlaps the respective uppermost and lowermost wedge-shaped reinforcing members 5 and terminates in a horizontally extending outflared lip 2d.

The complementary side wall-forming panels 2'-2' also present complementary laterally extending flange sections 10"-10" which together form the rear wall of the pilaster part P' of the unit. As shown in FIG. 34, the aligned and laterally extending flange section 10"-10" are integral with the front ends of the respective side wall-facing sections 2a-2a of the panels 2'-2', and the vertical and horizontal edges of the rear wall-forming flange sections 10"-10" present outturned edge forming

flanges 10b each of which terminates in a rearwardly flared lip 10c.

An outer facing pan 10 presents a front wall-forming section 10a, whose vertical length corresponding to the length of the laterally extending rear wall-forming sections 10" and whose transverse width corresponds to the distance between the vertical edges of the rear wall-forming sections 10"-10" presents inturned edge forming flanges 10b along both vertical and horizontal edges thereof which are complementary to the respective vertical and horizontally extending outturned flanges 10b associated with the rear wall-forming sections 10"-10" of the pilaster part. The inturned flanges 10b associated with the front facing pan 10, terminate in outflared lips 10c, and the adjacently paired lips 10c-10c are secured together by spot welds or bonding adhesive externally applied in the crotch defined between the adjacent outflared lips.

Before the front facing pan 10 is applied to the rear wall-forming sections 10"-10" of the pilaster, a reinforcing core 12, which may be formed of chemically treated corrugated paperboard, a fibreglass slab or other reinforcing material, is adhesively bonded to the front surfaces of the rear wall-forming sections 10"-10", and the rear face of the core 12 may also be adhesively bonded to the front ends of the horizontally extending wedge-shaped reinforcing members 5 which abut thereagainst as shown in FIG. 34. The outer face of the reinforcing core 12 is coated with adhesive and the applied outer facing pan 10 of the pilaster part is adhesively secured thereto. The edge forming flanges 10b of the outer facing pan 10 are then rigidly secured to the complementary edge forming flanges 10b of the rear wall-forming flange sections 10" and 10" as by welds or bonding adhesive externally applied to the crotch defined between the adjacent paired lip portions 10c-10c

thereof to provide a rigid pilaster unit. Semi-tubular edging strips 13, each presenting a curvilinear facing portion 13' and inturned locking lips 13" are then telescopically applied to both vertically and horizontally extending edges of the pilaster body, with the inturned lips 13" interlocked to the paired outflared lips 10c-10c extending along the vertical and horizontal edges of the pilaster body.

Prior to application of the semi-tubular edging strips 13 to the pilaster body, upper and lower cap members 6 are applied to the dividing partition forming part of the unit. Each of the cap members 6 is generally wedge-shaped in horizontal length and extends from the adjacent end of the web portion 1' of the channel-shaped base frame member 1 to the front end of the dividing partition forming part S' of the unit. Each of the cap members 6 may be V-shaped in transverse section as shown in FIGS. 30, 32, 33, 35, 36 and 37, to present tapered wedge-shaped side sections 6b-6b which together define an artistically shaped crown ridge extending along the medial center line of the dividing partition part. The side edges of each cap member present a pair of inturned lips 6a-6a which interlock with the outflared lips 2d-2d extending horizontally along the upper and lower ends of the side wall facing sections 2a-2a, when the cap members 6-6 are telescopically applied. The front end 6e of each of the V-shaped cap members 6 is coped as shown in FIG. 35 to interfit with the curvilinear shape of the adjacent horizontally extending semi-tubular edging strip 13 as applied to the respective upper and lower ends of the pilaster part.

It will also be appreciated that the upper and lower cap members 6-6 which are V-shaped in transverse section, and shown associated with the dividing partition part S' of FIGS. 30, 32, 33, 35, 36 and 37, may be replaced by relatively flat cap members 6'-6', constructed substantially as shown in FIGS. 16, 17, 19, 20 and 21, and each having a relatively flat facing section 6c presenting inturned lips 6a-6a along the tapered side edges thereof.

and which telescopically interlock with the outflared lips $2d-2d$ extending from the horizontal inturned flanges $2c-2c$ of the side wall-facing sections $2a-2a$ of the side wall-forming panels $2'-2'$ of the dividing partition part S' shown in FIG. 33. The rear end of such relatively flat cap member $6'$ would substantially overlap the adjacent end of the web portion $1'$ of the channel-shaped base frame member 1 of the dividing partition part S' as shown in FIG. 33, and the front end of each relatively flat cap member $6'$ would be coped to interfit with the respective horizontally extending semi-tubular edging strips 13 associated with the pilaster part P' of the unit.

Alternatively, the complementary side wall facing sections $2a-2a$ of the side wall-forming panels $2'-2'$ associated with the dividing partition part S' as shown in FIGS. 33, 36 and 37, may present paired wedge-shaped inturned flanges $2c'-2c'$ along the upper and lower ends of their facing sections $2a-2a$, and which terminate in adjacent outflared lips $2d-2d$ externally bonded together and extending along the medial center line of the dividing partition part, as indicated in FIGS. 23, 24, 26, 27 and 28. In such case, the adjacently paired outflared lips $2d-2d$ are covered and concealed by a cap member $6''$ of semi-tubular form which presents a curvilinear outer face $6d$ and inturned locking lips $6a-6a$, as illustrated in FIGS. 23 and 24, which interlock with the adjacently paired outflared lips $2d-2d$ of the side wall-forming panels $2'-2'$ of the dividing partition part S' . The rear end of each semi-tubular cap member $6''$ would be made to substantially overlap the adjacent end of the web portion $1'$ of the channel-shaped base frame member 1 of the dividing partition part S' shown in FIG. 33, and the front end thereof would be coped to interfit with the adjacent horizontally extending edging strip 13 of the pilaster part P' .

The dividing partition and pilaster unit illustrated in FIGS. 30-38, equipped with upper and lower cap members $6-6$ which are V-shaped in transverse section, or equipped with upper and lower cap members $6'-6'$ which are substantially flat in transverse section, or equipped with cap members in the form of horizontal edging strips $6''$ interlock to the paired outflared lips $2d-2d$ extending from the upper and lower wedge-shaped flanges $2c'-2c'$ of the side wall-forming panels $2'-2'$; has great strength and resistance to downsag, sidesway, bending, warping, twisting and deformation strains. The enhanced strength and resistance to deformation strains possessed by this dividing partition and pilaster unit, is partly attributable to the pilaster forming flange sections $10''-10''$ which are integral with and extend laterally from the side wall-facing sections $2a-2a$ of the dividing partition part S' , and because the pilaster forming flange sections $10''-10''$ forming the rear wall of the pilaster part P' are themselves reinforced by edge forming flanges $10b$ terminating in outflared lips $10c$ extending from the vertical and horizontal edges thereof. The construction is further reinforced by the front facing pan 10 having complementary inturned edge-forming flanges $10b$ terminating in outflared lips $10c$ which are externally bonded to the complementary outflared lips $10c$ of the laterally extending pilaster forming flange sections $10''-10''$ of the pilaster part P' .

The paired inturned flanges $2c-2c$ or $2c'-2c'$ extending horizontally along the upper and lower ends of the side wall-forming sections $2a-2a$ of the side wall-forming panels $2'-2'$, and which terminate in paired outflared lips $2d-2d$, also serve to further reinforce the side wall-forming panels $2'-2'$ against deformation strains. It will therefore be appreciated that when side wall-forming panels $2'-2'$ formed as above described, are assembled to the internal framework, comprising the channel-shaped base frame member 1 , the panel liners $4-4$, and the horizontally extending web-shaped bracing members $5-5$ as adhesively bonded together to provide a rigid framework as shown in FIGS. 31-38, an

integrally fabricated dividing partition and pilaster unit is provided which will withstand all normally expected downsag, sidesway, bending, warping, buckling, twisting and deformation strains, and without the use of an internal front frame member 3 positioned between the front ends of its side wall facing sections $2a-2a$.

When the dividing partition and pilaster unit as shown in FIGS. 31-38 may be subjected when installed to exceptionally severe use and abuse, as in schools and institutions, the dividing partition part S' of the unit may be further strengthened and reinforced by employing a U-shaped base frame as a part of its internal framework. The U-shaped base frame for the dividing partition and pilaster unit shown in FIGS. 31-38, may be constructed as shown in FIG. 13, and comprising a channel-shaped base frame member 1 having horizontally extending channel-shaped arms $9-9$ welded to the upper and lower ends thereof. In such construction, the inturned flanges $2c$ or $2c'$ extending from the horizontal upper and lower ends of the side wall-facing sections $2a-2a$ of the complementary side wall-forming panels $2'-2'$ as shown in FIGS. 34-38, would snugly overlap and may be adhesively bonded to the web portion $9'$ of such horizontally extending arms $9-9$, and with the panel liners $4-4$ adhesively bonded to the side edges of the spaced wedge-shaped bracing members 5 , and whose base ends would be adhesively bonded to the inner faces of the web portion $1'$ and side flanges $1''$ of the base frame member 1 , and whose front ends would be adhesively bonded to the exposed rear face of the pilaster core 12 , as previously described.

In such modified construction, the base sections of the uppermost and lowermost horizontally extending wedge-shaped bracing members 5 would be telescoped into the respective upper and lower channel-shaped arms $9-9$ as shown in FIG. 14, and adhesively bonded to the inner faces of the web portion $1'$ and side flanges $1''$ of the channel-shaped base frame member 1 , and to the interior faces of the web portion $9'$ and tapered side flanges $9''$ of the respective horizontally extending arms 9 . As also indicated in FIG. 14, the front sections of the uppermost and lowermost bracing members 5 , which extend forwardly from the front terminal ends of the respective channel-shaped arms 9 to the front end of the dividing partition part S' as shown in FIG. 33, may be thickened in transverse section so that the flat outer faces $5'$ thereof are substantially flush with the flat outer face of the web portions $9'$ of the arms 9 with which they are associated, and to thereby provide snug and flush seats for the entire length of the upper and lower inturned flanges $2c$ or $2c'$ extending from the upper and lower ends of the side wall-facing sections $2a-2a$ of the wall-forming panels $2'-2'$.

Alternatively, the dividing partition unit S shown in FIGS. 14-15B, or the dividing partition part P' of the partition and pilaster unit shown in FIGS. 30-38, may be modified to incorporate a U-shaped base frame as a part of the internal framework thereof which is shaped and constructed as shown in FIG. 43. The modified form of U-shaped base frame shown in FIG. 43 is composed of a channel-shaped base frame member $1a$ and generally channel-shaped arms $9a-9a$ extending forwardly from the upper and lower ends of the channel-shaped base frame members $1a$. Each arm $9a$ may be one to two feet long in horizontal length and presents a horizontally extending web defined by inclined facing portions $9a'-9a'$ joined by a flat crown portion $9b'$, and side flanges $9''-9''$ extending vertically from the inclined facing portions $9a'-9a'$. The inclined facing portions $9a'-9a'$ are generally wedge-shaped in horizontal length, and the side flanges $9''-9''$ have a slight forward taper conforming to the wedge-shaped form of the dividing partition unit S or the dividing partition part S' . The flat crown portion $9b'$ has a uniform width of approximately one to two inches, and inclines forwardly toward the front

end of the dividing partition unit S or dividing partition part S'.

The rear ends of the side flanges 9" of the horizontally extending arms 9a-9a abut and are welded to the front edges of the tapered side flanges 1" of the channel-shaped base frame member 1a adjacent the upper and lower ends thereof. The upper and lower end portions 1a'-1a' of the web portion 1' of the base frame member 1a are truncated in form to fit within the base ends of the inclined facing portions 9a'-9a' and crown portion 9b' of the horizontal arms 9a-9a as shown in FIG. 42, and the abutting ends then welded together. The side edges of the inclined facing portions 9a'-9a' of the horizontally extending arms 9a-9a also abut against and are welded to the terminal ends of the side flanges 1"-1" of the base frame member 1a, as shown in FIG. 43. The channel-shaped base frame member 1a and channel-shaped horizontally extending arms 9a-9a are preferably formed from heavy metal plate approximately one-eighth inch thick, and when these components are assembled as shown in FIG. 43, a U-shaped base frame for the dividing partition unit S or dividing partition part S' is provided of great strength.

The internal framework for the composite dividing partition and pilaster unit shown in FIGS. 41-47 also includes uppermost and lowermost wedge-shaped reinforcing members 5a-5a and intermediate wedge-shaped reinforcing members 5 as shown in FIGS. 42 and 43. The wedge-shaped reinforcing members 5 and 5a may be formed from a series of layers of corrugated paperboard adhesively bonded together and chemically treated for increased strength, heat resistance and resistance to shrinkage. The uppermost and lowermost wedge-shaped reinforcing members 5a are preferably shaped as shown in FIGS. 42 and 43 so that their inner end portions snugly fit within the horizontally extending arms 9a-9a of the base frame, with their side faces and outer faces adhesively bonded to the respective inner faces of the side flanges 9", inclined facing portions 9a'-9a' and crown portion 9b' of the horizontally extending arms 9a, and with the base ends of the uppermost and lowermost bracing members 5a-5a also adhesively bonded to the inner face of the adjacent truncated end portions 1a' of the channel shaped base frame member 1.

The front sections of the uppermost and lowermost bracing members 5a which extend from the front terminal ends of the horizontal arms 9a-9a to the front end of the dividing partition part S' may be thickened so that their outer faces 5a' and 5b' are made as a flush continuation of the outer faces of the inclined facing portions 9a'-9a' and flat crown portion 9b' of the horizontally extending arms 9a-9a. The intermediate wedge-shaped reinforcing or bracing members 5 may have a uniform thickness of approximately two inches, and the base ends thereof bonded to the inner faces of the web portion 1' and side flanges 1" of the channel-shaped base frame member 1a of the U-shaped base frame. The front ends of the wedge-shaped bracing members 5-5a are subsequently adhesively bonded to the rear face of the pilaster core 12 as shown in FIG. 46.

The complementary side wall-forming panels 2'-2' of the dividing partition and pilaster unit shown in FIGS. 41-47 together present complementary side wall-facing sections 2a-2a which form the exterior side walls of the dividing partition part S' of the unit, and complementary laterally extending flange sections 10"-10" which form the rear wall of the pilaster part P'. The upper and lower ends of the side wall-facing sections 2a-2a also present complementary inclined cap-forming sections 2c"-2c" as shown in FIGS. 41-45, and which are wedge-shaped in horizontal length and designed to snugly overlap the adjacent inclined facing portions 9a'-9a' of the horizontal arms 9a, and the exposed face portions 5a'-5a' of the respective uppermost and lowermost wedge-shaped bracing members 5a-5a. The comple-

mentary cap-forming portions 2c"-2c" terminate in complementary inturned flanges 2c'''-2c''' each having a uniform width of approximately one-half to one inch, and which are designed to snugly overlap the flat crown portion 9b' of the adjacent horizontal arm 9a of the base frame, and to also overlap the exposed flat crown portion 5b' of the adjacent uppermost or lowermost wedge-shaped bracing member 5a. The inner ends of the in-turned flanges 2c'''-2c''' terminate in a pair of horizontally extending outflared lips 2d-2d which are secured together by welds or bonding adhesive externally applied in the crotch defined between the adjacently paired outflared lips 2d-2d.

The vertical base end of each side wall-facing section 2a presents an inturned flange 2b which overlaps and is welded or rigidly secured to the rear face of the web portion 1' of the channel-shaped base frame member 1a as shown in FIG. 46, and the base end of each inclined cap forming section 2c" also preferably presents a similar inturned flange which is welded or otherwise rigidly secured to the rear face of the adjacent truncated end portion 1a' of the channel-shaped base frame member 1a. A cap member 6" in the form of a semi-tubular edging strip, and presenting a curvilinear facing portion 6d and inturned lips 6a is telescopically applied and interlocked to the paired outflared lips 2d-2d which extend along the medial center line of the dividing partition part. Each cap member 6" extends from the truncated end portion 1a' of the channel-shaped base frame member 1 to the front end of the dividing partition part S'. As shown in FIGS. 41, 44 and 47, the front end of each cap member 6" has a coped formation 6f to interfit with the adjacent horizontally extending edging strip 13 which is subsequently applied to the pilaster part of the unit.

The side wall-facing section 2a of each of the side wall-forming panels 2' has a panel liner 4 adhesively bonded thereto and which has a thickness substantially equal to or only slightly greater than the thickness of the side flanges 1" and 9" of the U-shaped base frame. Each panel liner 4 is so dimensioned as to substantially abut the inner edge of the adjacent side flange 1" of the base frame member 1a and the inner edges of the adjacent side flange 9" of the horizontal upper and lower arms 9a-9a of the U-shaped base frame, as shown in FIGS. 42 and 46. The front end of each panel liner 4 also substantially abuts the inner face of the pilaster core 12 as shown in FIG. 46. The inner face of each panel liner 4 is adhesively bonded to the adjacent side faces of the uppermost and lowermost wedge-shaped bracing members 5a and to the adjacent side faces of the intermediate wedge-shaped bracing members 5. An extremely strong dividing partition part is thus provided.

When the internal framework of the dividing partition unit S as shown in FIGS. 13-15B is modified to incorporate a U-shaped base frame, upper and lower horizontally extending bracing members 5a and intermediate bracing members 5, constructed as shown in FIG. 43, it will be appreciated that, in such modified dividing partition unit, the front ends of the horizontally extending wedge-shaped bracing members 5a and 5 would be adhesively bonded to the rear face of the vertical front frame member 3 as shown in FIG. 14. Additionally, the side wall facing panels 2-2 of such modified dividing partition unit would also present complementary inclined cap forming portions 2c"-2c" which are wedge-shaped in horizontal length, and designed to snugly overlap the adjacent inclined facing portions 9a'-9a' of the horizontal arms 9a and the exposed facing portions 5a'-5a' of the respective uppermost and lowermost wedge-shaped bracing members 5a-5a as illustrated in FIG. 41. The complementary cap-forming portions 2c"-2c" would also present complementary inturned flanges 2c'''-2c''' each having a uniform width of approximately one-half to one inch, and designed to snugly overlap the flat crown portion 9b' of the adjacent horizontal arm 9a of the base

frame and to also overlap the exposed flat crown portion $5b'$ of the adjacent uppermost and lowermost wedge-shaped bracing member $5a$. The paired inturned flanges $2c'''-2c'''$ would also terminate in a pair of horizontally extending outflared lips $2d-2d$ secured together by welds or bonding adhesive externally applied to the crotch defined between the adjacently flared lips $2d-2d$, and the adjacent flared lips $2d-2d$ would be covered by a semi-tubular cap member $6''$ as shown in FIGS. 14 and 15 whose front end is coped to interfit with the adjacent end of the vertically extending front edging strip 7 , and the abutting ends thereof then welded together to form finished corners $7e$ for the so modified dividing partition unit S illustrated in FIGS. 23 and 26.

The pilaster forming part P' for the dividing partition and pilaster unit shown in FIGS. 41-47 is constructed substantially as shown in FIGS. 38 and 46. A reinforcing core 12 is adhesively bonded to the inner face of the aligned and laterally extending flange sections $10''-10''$ of the side wall-forming panels $2'-2'$, and the core 12 is also preferably adhesively bonded to the adjacent ends of the horizontally extending wedge-shaped bracing members 5 and $5a$ and the front ends of the panel liners $4-4$ as shown in FIG. 46. The outer face of the pilaster reinforcing core 12 is coated with adhesive to bond thereto the inner face of the front facing pan 10 of the pilaster as telescoped thereover. The paired outflared lips $10c-10c$ associated with the complementary edge-forming flanges $10b-10b$ which extend from the vertical and horizontal edges of the front facing pan 10 and the rear wall-forming flange sections $10''-10''$ of the pilaster part P' are also rigidly secured together to provide a strong pilaster body, as by welds or bonding adhesive externally applied in the crotch defined between the adjacently paired outflared lips $10c-10c$ thereof.

As shown in FIGS. 41, 44 and 47, semi-tubular edging strips 13 are telescoped over the paired outflared lips $10c-10c$ extending along the vertical and horizontal edges of the pilaster body to provide a finished pilaster part P' . The front ends of the upper and lower semi-tubular cap members $6''-6''$, applied to the dividing partition part S' along the medial center line thereof, are provided with coped front ends $6f$ which interfit with and are welded to the respective upper and lower horizontally extending semi-tubular edging strips 13 applied to the pilaster part P' .

The dividing partition and pilaster unit constructed as shown in FIGS. 41-47 and above described has tremendous strength and ability to resist the most vigorous bending, warping, twisting and deformation strains which may be imposed thereon. In addition to the reinforcing attributes of the internal U-shaped base frame and the horizontally extending wedge-shaped bracing members 5 and $5a$ constructed as shown in FIG. 43; the panel liners $4-4'$ and the pilaster part P' of the unit also greatly reinforce the construction. Additional reinforcing is contributed by the cap-forming portions $2c''-2c''$, the associated inturn flanges $2c'''-2c'''$ and the weldably jointed outflared lips $2d-2d$ which form an integral part of the complementary side wall-forming panels $2'-2'$. The dividing partition and pilaster unit constructed as shown in FIGS. 41-47 may nevertheless be economically manufactured and assembled, and is relatively light in weight when the horizontally extending wedge-shaped bracing members 5 and $5a$, the panel liners $4-4'$ and the pilaster core 12 are formed from chemically treated corrugated paperboard.

The prefabricated door D , as shown in FIGS. 1-2 and FIGS. 30-31, is swingably supported by an upper hinge bracket 21 and a lower hinge bracket 23 whose respective saddle parts $21'$ and $23'$ are rigidly secured to a vertical jamb edge of the pilaster unit P as shown in FIGS. 1 and 2, or the pilaster part P' as shown in FIGS. 30-31. The upper and lower hinge brackets 21 and 23 each present a hinge arm 22 extending forward-

ly from the respective saddle sections thereof as shown in FIGS. 1 and 30. A door stop 24 has a similar saddle part $24'$ rigidly secured to the opposite vertical edge of one or all pilaster units P or pilaster parts P' , and presents a striker arm $25'$ extending forwardly from its saddle part, as shown in FIGS. 1 and 30.

Each prefabricated and predimensioned door D should snugly fit within the door opening defined between adjacent pilaster units P or adjacent pilaster parts P' of the respective cubicle sections of the cubicle assembly shown in FIG. 1 or FIG. 30. To provide precisely dimensioned door openings to snugly receive the prefabricated door or doors D between adjacent pilaster units P or pilaster parts P' , it is of the utmost importance that the base ends of each and all of the dividing partition units S or dividing partition parts S' as heretofore described, be accurately leveled as by leveling and tension pads T or T' so as place and maintain the medial center lines thereof in precise parallelism; and further, that the base ends of the respective dividing partition units S or dividing partition parts S' be so rigidly anchored to the vertical room wall V , as by anchoring means A, A', A'' or A''' that no dimensional change in the door opening or openings occur during years of use and abuse of the installation.

Each prefabricated door D may comprise a door body approximately one inch thick and formed from a pair of complementary facing pans 30 having a reinforcing and sound deadening core sandwiched therebetween and preferably composed of chemically treated corrugated paperboard to provide a relatively light but strong door body. The complementary facing pans 30 present complementary inturn edge-forming flanges along the vertical and horizontal ends thereof, which terminate in adjacent outflared lips externally bonded together, and covered by vertical and horizontally extending edging strips whose adjacent corner forming ends are interfitted and welded together to provide strong finished corners for the door body. As shown in FIGS. 1 and 30, an S -shaped door bracket 31 may be inset into the vertical hinging edge of the door body adjacent the upper end thereof which receives the hinge arm 22 of the pilaster supported upper hinge bracket 21 . An angle shaped lower door bracket 32 is fixed to the lower rear corner of the door body and receives the hinge arm 22 extending from pilaster supported lower hinge bracket 23 . An upper hinge pintle extends through the hinge arm 22 of the upper hinge bracket 21 and is supported by the S -shaped door bracket 31 . The door body, the upper S -shaped door bracket 31 , and the lower angular shaped door bracket 32 may be constructed as disclosed and described in U.S. Patent 3,056,475. A lower hinge pintle, fixed to the arm 22 of the lower hinge bracket 23 , extends through the lower door bracket 32 and into the door body, and door operating means concealed within the door body and associated with the lower hinge pintle and lower door bracket 32 may be provided to automatically swing the door into closed position. Such door operating means may be constructed as described in U.S. Patent 3,026,599 or U.S. Patent 3,107,758.

The door D as shown in FIGS. 1 and 30, may also contain a concealed door latch assembly which may be constructed as described in U.S. Patent 2,876,873 or U.S. Patent 3,095,225 and whose lockbolt is retracted and extended by manual rotation of exposed escutcheon medallions 33 , as diagrammatically indicated in FIGS. 1 and 30, and which are associated with the concealed door latch assembly and operatively connected to the lockbolt. The door stop 24 , mounted on the jamb edge of the adjacent pilaster unit S or pilaster part S' , as shown in FIGS. 1 and 30, presents a pocket $24d$ formed in its saddle part $24'$ as shown in FIGS. 39 and 40, which receives the projected end of the lockbolt.

At the location where the upper hinge bracket 21 and lower hinge bracket 23 are to be applied to one of

the vertical jamb edges of the pilaster unit P or pilaster part P', the vertical jamb edge of the pilaster body as shown in FIG. 38 presents an upper seat formation 18 for the reception of the saddle part 21' of the upper hinge bracket 21, and a lower seat formation 19 for the reception of the saddle part 23' of the lower hinge bracket 23. The opposite vertical jamb forming edge of the pilaster body presents an intermediate seat formation 20 for the reception of the saddle part 24' of the door stop 24 as indicated in FIG. 38.

Each of the seat formations 18, 19 and 20 may have a vertical length of about two inches, and may be formed by cutting away the paired outflared lips 10c—10c of the pilaster body at the seat forming area, as generally illustrated in FIGS. 39 and 40, so that the terminal ends 10c'—10c' of the paired outflared lips 10c—10c and the terminal ends 13a—13a of the adjacent semi-tubular edging strips 13—13, define the upper and lower ends of the respective seat formations 18, 19 and 20. Each seat formation 18, 19 and 20 of the pilaster body is thus formed by exposed inturned flange portions 10b'—10b' whose inner ends terminate in relatively short and laterally flared rib portions which may be welded together to form a composite medially extending rib 14 on opposite sides of a circular hole 14a centrally formed in the exposed and complementary edge-forming flange portions 10b'—10b' of the pilaster body.

As shown in FIGS. 39—40C, the hardware element or door stop 24 may be integrally cast or molded to present a saddle part 24' having a base section 24a inserted between the adjacent terminal ends 10c'—10c' of the paired outflared lips 10c—10c of the pilaster body, and whose flat rear face is designed to snugly seat against the outer faces of the exposed inturned flange portions 10b'—10b' of the pilaster body. Upper and lower vertically extending grooves 24a' are formed in the rear face of the base section 24a into which the ribs 14 of the pilaster body snugly telescope. A circular boss portion 24b, extending from the rear face of the base section 24a, is shaped and designed to snugly project into the circular hole 14a formed in the exposed inturned flange portions 10b'—10b' of the pilaster body as shown in FIGS. 40 and 40B. The hardware element or door stop 24 also presents upper and lower lip portions 24c designed to overlap and snugly seat over the terminal ends 13a of the upper and lower edging strips 13, as shown in FIG. 40.

As shown in FIGS. 39, 40 and 40A, the saddle part 24' of the door stop 24 presents an exposed pocket 24d into which the terminal end of the lockbolt associated with the door body may retractably telescope. Where the extended end of the latch bolt is to provide the stop for the door when closed, the saddle part 24' of the door stop may present a door stop formation 25 which presents an abutment face 25a adjacent the pocket 24d as shown in FIGS. 39, 40 and 40A, and against which the latch bolt abuts. Alternatively, the saddle part 24' of the reversible door stop 24 may have a laterally offset and forwardly extending striker arm 25' against which the side face of the door may abut as shown in FIGS. 1 and 30.

The upper seat formation 18 of the pilaster body as illustrated in FIG. 38 is formed substantially as shown in FIG. 39, and the upper hinge bracket 21 presents a saddle part 21' which is similar to the saddle part 24' of the hardware element shown in FIGS. 39 and 40, except that the saddle part 21' of the upper hinge bracket 21 has no lockbolt receiving pocket but presents a continuous outer face having an integrally formed hinge arm 22 extending forwardly from the curvilinear front face thereof as indicated in the upper part of FIG. 38. The saddle part 21' of the upper hinge bracket 21 has a base section 24a inserted between the adjacent terminal ends 10c'—10c' of the paired outflared lips 10c—10c and the adjacent terminal ends 13a—13a of the upper and lower semi-tubular edging strips 13—13, and which define therebetween the seat formation 18 of the pilaster body. The

flat rear face of its base section 24a is designed to snugly seat against the outer faces of the exposed inturned flange portions 10b'—10b' which define the seat formation 18. A circular boss portion 24b, extending from the rear face of its base section 24a, is shaped and designed to snugly project into the circular hole 14a formed in the exposed flanges 10b'—10b' which define the seat formation 18 of the pilaster body. The saddle part 21' of the upper hinge bracket 21 also presents upper and lower lip portions 24c designed to overlap and snugly seat over the terminal ends 13a of the adjacent upper and lower edging strips 13. The base section 24a of the upper hinge bracket 21 is provided with upper and lower vertically extending grooves 24a' into which the ribs 14 forming a part of the seat formation 18 of the pilaster body snugly telescope.

The lower hinge bracket 23, designed for attachment to the angular lower seat formation 19 of the pilaster body as shown in FIG. 38, presents a front saddle part 23' from whose lower end of the hinge arm 22 thereof forwardly extends, and a rearwardly extending saddle part 23'' which overlaps the lower horizontal edge of the pilaster body. The angular shaped seat formation 19 is formed by exposed vertically extending and horizontally extending inturned flange portions 10b' and 10b' at the lower corner of the pilaster body, and which respectively present a vertically extending and horizontally extending medial rib 14. A circular hole 14a is formed in the vertically extending seat forming flange portions 10b' of the pilaster body, and the angular shaped lower seat formation 19 is defined between the terminal ends 10c' of the vertically extending outflared lips 10c of the pilaster body and the terminal ends 10c' of the horizontally extending outflared lips 10c of the pilaster body. The upper end of the vertically extending saddle part 23' of the lower hinge bracket 23 is provided with an upwardly extending lip portion 23c which overlaps the terminal end 13a of the vertically extending edging strip 13, and the terminal end of the horizontally extending saddle part 23'' of the lower hinge bracket 23 overlaps the adjacent terminal end 13a of the horizontally extending edging strip 13.

The vertically extending saddle part 23' and the horizontally extending saddle part 23'' of the lower hinge bracket 23 present an angular shaped base section 24a insertable between the adjacent terminal ends 10c'—10c' of the vertically extending outflared lips 10c—10c and the horizontally extending outflared lips 10c—10c of the pilaster body, and each of the angular extending base sections 24a presents a flat rear face designed to seat against the outer faces of the exposed vertically extending inturned flange portions 10b'—10b' and the exposed horizontally extending inturned flange portions 10b'—10b' of the pilaster body. The vertically extending base section 24a and the horizontally extending base section 24a are provided with vertically extending grooves 24a' into which the vertically extending rib 14 and the horizontally extending rib 14 of the pilaster body respectively telescope. A circular boss portion 24b extending from the rear face of the vertically extending base section 24a is shaped and designed to snugly project into the circular hole 14a formed in the exposed vertically extending inturned flange portions 10b'—10b' of the pilaster body.

The hardware elements which respectively form the upper hinge bracket 21, the lower hinge bracket 23 and the door stop 24 as above described, may be integrally cast or molded from a suitable metal or plastic at relatively low cost. Each of the hardware elements 21, 23 and 24 may be rigidly secured to the exposed inturned flange portions 10b'—10b' which define the respective seat formations 18, 19 and 20 of the pilaster body by means of a toggle clamp which includes a clamp block 26 shaped as shown in FIGS. 39 and 40 and which is supported by a clamp bolt 27 extending through a hole formed in the vertically extending base section 24a and associated circular boss portion 24 of the vertically ex-

tending saddle part 21' of the upper hinge bracket 21, the vertically extending saddle part 23' of the lower hinge bracket 23, and the vertically extending saddle part 24' of the door stop 24. The head 27a of the clamp bolt 27 for the door stop 24 is inset in the bottom wall of the lockbolt receiving pocket 24d as shown in FIGS. 39 and 40, so that it does not interfere with the movement of the latch bolt. The clamp bolt 27 for the upper hinge bracket 21 is positioned slightly above its hinge arm 22 as shown in the upper part of FIG. 38, and its head section 27a is inset in the front face of its saddle forming part 21' thereof but exposed for external manipulation. The clamp bolt 27 associated with the lower hinge bracket 23 is also positioned slightly above its hinge arm 22, and presents a head section 27a which is inset within its vertically extending saddle part 23' but exposed for external manipulation. All of the bolt heads 27a may be so shaped that they can be rotated in only one direction to prevent turning or tampering with the lockbolts when tightened to respectively secure the upper hinge bracket 21, lower hinge bracket 23 of the door stop 24, to the pilaster body.

To mount the hardware elements 21, 23 and 24 on the seat forming flange portions 10b'-10b' of the respective seat formations 18, 19 and 20 of the pilaster, each clamp bolt 27 is first inserted into the bore formed in the base section 24a and boss portion 24b of the hardware elements 21, 23 and 24, and the clamp block 26 is then applied to the threaded shank section 27b of the clamp bolt 27. The clamp block 26 of the assembled hardware unit may then be tilted and inserted through the hole 14a in the inturned seat forming flange portions 10b'-10b' of the pilaster to a position within the pilaster as shown in FIG. 40. The clamp block 26 presents a pair of relatively short legs 26a extending forwardly from the ends thereof as shown in FIGS. 40 and 40B. When the head portion 27a of the clamp bolt 27 is initially rotated, the clamp block 26 is initially rotated until its end faces 26b move into abutment against the inner side faces of the pilaster body. Continued rotation of the clamp bolt 27 draws the terminal leg portions 26a of the clamp block 26 forwardly into rigid abutment against the inner faces of the inturned flange portions 10b'-10b' of the pilaster body.

When the respective hardware elements 21, 23 and 24 are thus locked to the exposed inturned flange portions 10b'-10b' of the pilaster body, each circular trunnion forming boss portion 24b thereof is supported by the perimetrical edge of the circular hole 14a in the flange portions 10b'-10b' of the pilaster body. The respective hardware elements 21, 23 and 24 are prevented from movement and rotation by the upper and lower ribs 14 which interlock with the respective base sections 24a thereof. As thus constructed, the upper hinge bracket 21 and the lower hinge bracket 23 may be applied to respective seat formations 18 and 19 formed along either vertical edge of the pilaster body, and the door stop 24 may also be reversibly applied to the seat formation 20 formed along either vertical edge of the pilaster body to present its striker arm 25' or striker abutment 25 on either side of the pilaster to thereby accommodate either a right or a left hand swinging door.

Since the pilaster bodies for the pilaster units P shown in FIGS. 1, 2, 3, 4, 6 and 8, and the pilaster parts P' shown in FIGS. 30, 31, 32, 33, 34, 35 and 38, are finished by semi-tubular edging strips 13 extending along the vertical and horizontal edges thereof, the length of the respective edging strips must be such that their adjacent ends 13a define the upper and lower seat formations 18 and 19 which receive the respective upper and lower hinge brackets 21 and 23, and define the seat formation 21 which receives the reversible door stop 24. The vertical and horizontally extending edging strips 13 must also provide finished corners at the two upper corners and one lower corner of the pilaster body, where the adjacent

ends of the edging strips are in mitred abutment and welded together.

As illustrated in FIGS. 38 and 38A, the series of edging strips 13 may comprise a relatively short vertical edging strip 13b which may be first telescopically applied to the corresponding outflared lips 10c-10c of the pilaster, with its upper mitre cut end 13''' extending diagonally from the upper rear corner of the pilaster and with its lower end 13a forming the upper end of the seat formation 18. A longer vertical edging strip 13c may be telescopically applied to the corresponding vertically extending outflared lip 10c-10c by telescopic application of the edging strip 13c to the lower end of the pilaster body, and which edging strip 13c is of such length that its upper terminal end 13a forms the lower end of the upper seat formation 18 and its lower terminal end 13a forms the upper end of the lower seat formation 19. A pair of upper and lower edging strips 13d and 13e may then be telescopically applied to the paired outflared lips 10c-10c 20 extending along the opposite vertical edge of the pilaster body, with the adjacent ends thereof 13a temporarily overlying the intermediate seat formation 20, and so that the mitred outer ends 13''' of the edging strips 13d and 13e extend short of the adjacent upper and lower corners 25 of the pilaster body.

The upper and lower edging strips 13f and 13g may then be telescopically applied to the outflared lips 10c-10c extending along the upper and lower horizontal ends of the pilaster body. In this operation, the forward mitred end 13''' of the upper edging strip 13f is brought into abutment with the upper mitred end 13''' of the relatively short edging strip 13b, and the joint as thus formed is welded to provide a finished pilaster corner. The advance end 13a of the applied lower horizontal edging strip 13g defines the adjacent end of the angular seat formation 19, and its mitred front end 13''' extends diagonally from the opposite lower corner of the pilaster body. The upper and lower vertical edging strip 13d and 13e may then be driven outwardly to place their outer mitred ends 13''' 35 in mitre match with the adjacent mitred ends 13''' of the respective upper and lower horizontal edging strips 13f and 13g, and the corner joints as thus formed welded together to form finished upper and lower front corners for the pilaster body. The intermediate seat formation 20 to 40 which the door stop 24 is applied, is then exposed and defined between the spaced inner ends 13a-13a of the upper and lower edging strips 13f and 13g. The upper hinge bracket 21, the lower hinge bracket 23 and the reversible door stop 24 may then be applied and secured to the respective seat formations 18, 19 and 20 in the manner heretofore described.

When applying the upper and lower horizontal edging strips 13f and 13g to the pilaster part of the construction illustrated in FIGS. 35 and 47, the horizontally applied upper and lower edging strips 13f and 13g can be telescoped under the front coped ends 6e of the previously applied upper and lower cap members 6 as shown in FIG. 35, or the coped front ends 6f of the previously applied semi-tubular cap members 6'' as shown in FIG. 47, and 55 the respective joints thus formed are then welded to provide a strong and finished dividing partition and pilaster unit.

Prior to the mounting of the base end of the respective dividing partitions S constructed as shown in FIGS. 1-29 and previously described, or the respective dividing partition part S' as illustrated in FIGS. 30-38 and FIGS. 41-47 and previously described; a series of tension pads T constructed as shown in FIGS. 12-12A, or a series of tension pads T' constructed as shown in FIGS. 48-48A, 70 are adjustably secured to the web portion 1' of the channel-shaped base frame member 1 or 1a of the dividing partition. Each of the tension pads T and T' presents a threaded stud 35 which is inserted into a threaded hole 35' formed in the web portion 1' of the base frame member 1, as shown in FIGS. 5, 6, 7, 8, 9, 10, 11, 13, 14, 15, 75

16, 17, 19, 24, 26, 33, 34 and 37; or inserted in a threaded hole 35' formed in the web portion 1' of the channel-shaped base frame member 1a as shown in FIGS. 40, 43, 44, 45 and 46 of the accompanying drawings. By referring to these figures, it will be noted that a pair of transversely spaced threaded holes 35'-35' are located adjacent the upper end of the base frame member 1 or 1a, a pair of transversely spaced threaded holes 35'-35' are located adjacent the lower end of the channel-shaped base frame member 1 or 1a, and that one or more pairs of transversely spaced threaded holes 35'-35' are located in the intermediate area of the web portion 1' of the base frame member 1 or 1a.

The threaded stud 35 of the tension pad T as shown in FIGS. 12-12A has a polygonally shaped head section 35a and a deformable end extension 35b. The head section 35a presents a flared flange 35c against which the bottom wall 36' of a pad receiving cup 36 abuts, as shown in FIG. 12A. The deformable end extension 35b of the stud 35 extends through an axial hole in the bottom wall 36' of the pad receiving cup 36 so that the cup 36 is rotatably journaled on the deformable end extension 35b of the threaded stud 35. A circular pad 37 fitted within the circular rim 36" of the cup 36, may be adhesively secured to the cup and/or may be held in mounted relation thereto by an expansible retainer ring 38 which is embedded in the pad 37 and journaled on the deformable end extension 35b of the stud 35. The pad 37 has an axial hole 37' therein which exposes the terminal end of the deformable end extension 35b of the stud 35. The deformable terminal end of the end extension 35b is laterally deformed by the application of a swedging tool thereto, and the terminal end as thus deformed maintains the cup 36 and pad 37 rotatably journaled on the trunnion forming end extension 35b of the stud 35. The pad 37 may be formed of cast metal, hard rubber, plastic composition, or other material which has a small compressibility factor, and which will not deteriorate, weaken or shrink during a lifetime of use.

Tension pads T' constructed as shown in FIGS. 48-48A, and applied in paired spaced arrangement to the web portion 1' of the channel-shaped base frame member 1 or 1a of the dividing partition, may also be advantageously used. Each tension pad T', presents a threaded stud 35 having an enlarged neck section 35d whose outer face is welded or otherwise rigidly secured to the inner face of the bottom wall 39' of a cup-shaped metal pad member 39, whose rim 39" is of polygonal shape so that a wrench may be applied thereto.

To maintain the respective pilaster units P or pilaster parts P' of the cubicle assemblies shown in FIGS. 1-2 and FIGS. 30-31 in precise alignment, with adjacent pilasters in precise spaced relation to provide a precisely dimensioned door opening therebetween into which a prefabricated door D can be precisely fitted, the base end of each dividing partition unit S or dividing partition part S' must be leveled and rigidly anchored in cantilever suspension to the vertical room wall in a manner to prevent sidesway or down sag of any and all of the dividing partitions which form a part of the cubicle assembly.

At least one vertical wall of the interior room in which the cubicle assembly is to be installed is normally composed of an inner vertical wall V and an outer vertical wall V' spaced from the inner vertical wall V to provide an interior space V" through which water, sewage and other service piping and conduits may extend, as illustrated in FIGS. 49, 50 and 51. The inner vertical wall V on which the base ends of the dividing partitions S or S' are to be mounted, is preferably of masonry construction, and composed of monolith concrete as shown in FIGS. 50 and 51, or erected from strong building blocks with strong mortised joints as shown in FIG. 49. The masonry inner room wall V is usually approximately four inches in thickness, is faced with wall tile Vt, and is anchored to the room floor and ceiling to provide a strong and rigid

wall construction which will not buckle, crack or weaken when heavy cantilever loads are applied thereto.

In cases where the vertical masonry wall V, which is to support the cubicle assembly in cantilever suspension, has not yet been erected, anchoring means A may be built therein during the masonry construction thereof, as illustrated in FIGS. 2, 6, 8, 9, 10, 11, 33, 34 and 44. The anchoring means A may include a heavy gauge backing plate 40 cemented or otherwise bonded to the rear face of the room defining vertical masonry wall V, and is positioned directly opposite the location where the base end of the dividing partition unit S or dividing partition part S' is to be mounted on the tiled face Vt of the inner vertical room wall V. The backing plate 40 has a transverse width equal to or greater than the transverse width of the base end of the dividing partition, and has a vertical length substantially corresponding to the vertical height of the base end of the dividing partition as shown in FIG. 8, or may have a substantially greater vertical length so that its lower end is at least partly supported from the building floor. If desired, the upper end of the backing plate 40 may extend to and be anchored to that portion of the building ceiling which traverses the pipe space V". The backing plate 40 may also be channel-shaped in cross section, with the web portion thereof bonded to the inner face of the vertical masonry wall V.

Three or more pairs of spaced anchor bolts or tie rods 41, as shown in FIGS. 8-11, are cemented into the vertical masonry wall V during construction thereof and extending horizontally therethrough. The paired anchor bolts or rods 41 also extend through conforming holes formed in the backing plate 40 and present base heads or nuts 41', which brace against the adjacent face of the backing plate 40. A heavy gauge frontal plate 42, having a vertical length and a transverse width which substantially corresponds to the vertical height and width of the base end of the dividing partition, is applied to the tiled face Vt of the vertical masonry wall V after it has been erected. The frontal plate 42 may be directly bonded as by epoxy resin to the facing surface of the wall tile Vt, but preferably a compression pad 43 formed of hard rubber or the like, and having a thickness in the order of one-sixteenth to one-eighth of an inch, is first adhesively bonded to the facing tile Vt, and the rear face of the frontal plate 42 then adhesively bonded to the front face of the compression pad 43. The compression pad 43 has substantially the same length and width as the frontal plate 42 so as to be substantially covered thereby, as shown in FIGS. 8-11.

Each of the paired anchor bolts or tie rods 41 extends through an aligned hole formed in the compression pad 43 and frontal plate 42. A clamp nut 44 is applied to each anchor bolt or tie rod 41 and is tightened to rigidly clamp the backing plate 40 and the companion pad 43 and frontal plate 42 to the opposite sides of the vertical masonry wall V and associated tilting Vt. A series of threaded studs 45, each of which may form an end extension of the respective anchor bolts 41, extend forwardly from the frontal plate 42 and through a vertically elongated slot hole 45' formed in the web portion 1' of the channel-shaped base frame member 1 or 1a. The elongated slot holes 45' are arranged in transversely spaced pairs as shown in FIGS. 5, 7, 14, 15, 17, 19, 24 and 26, with each pair of holes 45'-45' positioned adjacent the correspondingly paired threaded holes 35'-35' formed in the web portion 1' of the channel-shaped base frame member 1 or 1a of each dividing partition, and through with each pair of holes 45'-45' positioned adjacent the which the correspondingly paired threaded studs 45 project. The paired holes 45'-45' are preferably vertically elongated in form to permit vertical adjustment of the respective dividing partitions as may be required, prior to permanent securement of the base ends of the dividing partitions to the threaded stud extensions 45 of the anchor

bolts or tie rods 41. As illustrated for example in FIG. 5, the paired threaded holes 35'-35' are preferably transversely spaced a further distance apart than the adjacent pair of anchor stud receiving slots 45'-45'.

Before the dividing partition is mounted on the vertical room wall, the threaded stud or shank sections 35 of the tension pads T or T' are externally threaded into the respective threaded holes 35' of the channel-shaped base frame member, as shown for example in FIGS. 7, 19, 26, 36, 37, 44 and 46. A base nut 46 is threadably applied to each threaded anchoring stud 45, a grip washer 46' is applied to each base nut 46, and the dividing partition is then erected by telescoping the paired stud receiving holes 45'-45' over the threaded anchoring studs 45. The base nuts 46 and associated grip washers 46' serve to space the rear face of the web portion 1' of the channel-shaped base frame member 1 or 1a of the dividing partition from the tiled face Vt of the vertical room wall V for a distance in the order of two to three inches. As illustrated for example in FIG. 8, this spacing permits external manipulation of the base nuts 46, as well as external rotation of the threaded shanks 35 of the leveling and tension pads T by the application of a wrench to the polygonal head section 35a thereof, or external rotation of the threaded shanks 35 of the leveling and tension pads T' by the application of a wrench to the polygonally shaped cup member 39 thereof.

A lock washer 47 and a lock nut 48 are then applied to that part of the respective threaded studs 45 which project within the channel-shaped base frame member 1 or 1a of the dividing partition. The lock nuts 48 are externally manipulated to tighten the same and to rigidly clamp the web portion 1' of the channel-shaped base frame member 1 or 1a between the exterior base washer 46' and the interior lock washer 47. The lock nuts 48 may be externally manipulated by a suitable wrench insertable through the adjacent rectangular openings 48' formed along the rear vertical ends of the side wall-forming sections 2a-2a of the side wall-forming panels 2-2 or 2'-2' of the dividing partition, and which rectangular shaped holes 48' are in alignment with corresponding rectangular shaped holes 48'-48' formed in the side flanges 1" of the channel-shaped base frame member 1 or 1a of the dividing partition.

The base end of each dividing partition unit S or dividing partition part S' is leveled by rotating the shank sections 35 of the leveling and tension pad T or T'. In the case of the tension pads T shown in FIGS. 12-12A, a wrench is applied to the polygonal head section 35a to rotate the stud or shank section 35 thereof in a manner to place the non-rotatable pad 37 thereof in bracing relation against the frontal plate 42. Each tension pad T' is rotated by a wrench applied to the polygonally shaped cup member 39 thereof, to place the bottom wall 39' of its cup member 39 in bracing relation against the frontal plate 42.

When the base end of the dividing partition has been vertically and laterally leveled, by suitable external manipulation of the tension pads T or T', the base nuts 46 and lock nuts 48 are re-adjusted to rigidly clamp the web portion 1' of the channel-shaped base frame member 1 or 1a of the dividing partition between the grip washers 46' and the lock washers 47. Thus, by a proper manipulation of the leveling and tension pads T or T', accompanied by a proper vertical adjustment of the dividing partition and proper manipulation of the base nuts 46 and lock nuts 48, the base end of each dividing partition may be rigidly anchored to the vertical room wall V without sidesway or down sag of the dividing partition, and with the assurance that the associated front wall-forming panels or pilaster units P or pilaster parts P' of the installed cubicle assembly are in true alignment, with adjacent pilasters defining precisely dimensioned door openings into which the cubicle doors D may be precisely fitted.

In cases where the inner vertical masonry wall V which

is to support the cubicle assembly in cantilever suspension, has not been erected, modified anchoring means A' may be built therein during the masonry construction thereof as illustrated in FIGS. 49, 49A and 49B. The built-in anchoring means A' comprises a series of angular anchor plates 50 whose horizontal legs 50' are implanted in vertically spaced relation in the interior room wall V during construction thereof, and with the vertical legs 50" of the angular plates 50 in bracing relation against the rear face of the masonry room wall V. Each anchor plate 50 has a pair of transversely spaced anchor bolts or rods 51, which may be welded or otherwise rigidly secured to the horizontal leg 50' thereof as shown in FIG. 48, and whose threaded front end projects through the tile face Vt of the vertical masonry wall V.

A heavy gauge frontal plate 42, having a vertical length and transverse width which substantially corresponds to the vertical height and width of the base end of the dividing partition, is applied to the tile face Vt of the vertical masonry wall V after it has been erected. The frontal plate 42 may be directly bonded as by epoxy resin to the facing surface of the wall tile Vt, but preferably a compression pad 43 formed of hard rubber or the like and having a thickness in the order of one-sixteenth to one-eighth of an inch, is first adhesively bonded to the facing tile Vt, with the rear face of the frontal plate 42 bonded to the front face of the compression pad 43. The compression pad 43 has substantially the same width and length as the frontal plate 42 as shown in FIG. 49.

Each of the anchor bolts or tie rods 51 extends through an aligned hole formed in the compression pad 43 and frontal plate 42. A clamp nut 44 is applied to the threaded projecting portion of each anchor bolt or tie rod 51 and is adjusted to tightly and rigidly clamp the compression pad 43 and frontal plate 42 to the tile face Vt of the masonry wall V. A series of threaded studs 45, which may form a continuation of the anchor bolts 51, or which may be alternatively rigidly welded or otherwise secured to the frontal plate 42 as shown in FIG. 49, extend forwardly from the frontal plate 42 and through the vertical elongated slot holes 45' formed in the web portion 1 of the channel-shaped base frame member 1 or 1a, as previously described.

Before the dividing partition unit S or dividing partition part S' is mounted on the vertical room wall V, the threaded stud or shank sections 35 of the tension pads T or T' are externally threaded into the respective threaded holes 35' of the channel-shaped base frame member 1 or 1a. A base nut 46 is threadably applied to each threaded anchoring stud 45, a grip washer 46' is applied to each base nut 46, and the dividing partition is then erected by telescoping the paired stud receiving holes 45'-45' over the threaded anchoring studs 45. The base nuts 46 and associated grip washers 46' serve to space the rear face of the web portion 1 of the channel-shaped base frame member 1 or 1a of the dividing partition from the tile face Vt of the vertical room wall V for a distance in the order of two or three inches.

A lock washer 47 and a lock nut 48 are then applied to that part of the respective threaded studs 45 which project within the channel-shaped base frame 1 or 1a of the dividing partition. The lock nuts 48 are externally manipulated to rigidly clamp the web portion of the channel-shaped base frame member 1 or 1a between the exterior base washers 46' and the interior lock washers 47. The lock nuts 48 are readily accessible for external manipulation by a suitable wrench inserted through the rectangular openings 48' of the dividing partition. The base end of each dividing partition unit S or dividing partition part S' is vertically and laterally leveled by rotating the shank sections 35 of the leveling and tensioning pads T or T' which are accessible for external manipulation by a suitable wrench inserted in the space between the base end of the dividing partition and the tile face Vt of the vertical room wall.

When the base end of the dividing partition has been vertically and laterally leveled by external manipulation of the tension pads T or T', the base nuts 46 and lock nuts 48 may be re-adjusted as required to rigidly clamp the web portion 1' of the channel-shaped base frame member 1 or 1a of the dividing partition between the grip washer 46' and the lock washer 47; thereby precisely leveling and rigidly anchoring each dividing partition to the vertical room wall, with the center lines of the dividing partition units S or dividing partition parts S' in precise parallelism.

In cases where the anchoring means must be applied to a preconstructed room wall V as shown in FIGS. 50 and 51, the structural strength of the preconstructed room wall must be taken into account. When the inner vertical wall V is constructed of monolith concrete or strong building blocks bonded together by strong mortise joints, the frontal plate 42 may have substantially the same vertical length as the height of the base end of the dividing partition to be applied thereto, and may be bonded as by epoxy resin 43' to the tile face Vt of the wall. When the vertical room wall V on which the dividing partitions are to be mounted may weaken from possible use and abuse to which the wall suspended cubicle installation may be subjected, the lower end of the frontal plate 42 may be made to extend to and be secured to the room floor, and for additional strength, the upper end of the frontal plate 42 may extend to and be secured to the room ceiling. To conceal the upper and lower ends of such floor to ceiling frontal plate 42, the rear face may be embedded in, and secured as by epoxy resin directly to, the vertical room wall V and the projecting upper and lower ends of the full length frontal plate 42 covered with facing tile to conceal the same.

Before the frontal plate 42 is bonded by epoxy resin to the tiled face Vt of the vertical room wall V as shown in FIG. 50, or alternatively, before the full length frontal plate is bonded as by epoxy resin directly to the front face of the vertical wall V, a series of transversely spaced holes Va are bored through the vertical room wall V as shown in FIG. 50B which receive the anchoring means A'' as shown in FIGS. 50, 50A and 50B. The anchoring means A'' comprises a series of transversely spaced wing bolts 55 having a pair of resiliently expandable wings 56 pivotally connected to the inner end of the shank 55' of the wing bolts. Each wing bolt 55 is so made that it may be telescoped through the bore Va of the wall V as shown in FIG. 50B, and during this insertion the paired wings 56 are collapsed by the wall of the bore Va until the wings emerge from the inner end of the bore, whereupon the wings 56 resiliently expand to a position normal to the bolt shank 55'. When resiliently expanded the wings 56 brace against the bolt shank 55' to maintain them in rigidly expanded position. When the bolt shank 55' is drawn forwardly, the expanded wings 56 of the wing bolt will brace against the inner face of the vertical room wall V.

After insertion of the wing bolts 55 in the respective bores Va of the wall V each of the bores Va are filled with strong bonding cement or adhesive such as epoxy resin 43', and a coating 43' of bonding cement or adhesive is also applied to the front surface of the tile face Vt, or directly to the vertical wall V. The frontal plate 42 is then telescoped over the projecting ends of the bolt shanks 55' and clamp nuts 44 are applied thereto to rigidly anchor the frontal plate 42 to the tile face Vt or directly to the room wall V. A series of threaded studs 45 which may form a continuation of the wing bolts 55 as shown in FIGS. 50 and 50A, or alternatively rigidly welded or otherwise secured to the frontal plate 42, extend forwardly from the frontal plate 42 and through the vertically elongated holes 45' formed in the web portion 1' of the channel-shaped base frame member 1 or 1a.

Before the dividing partition unit S or dividing partition part S' is mounted on the vertical room wall V, the

threaded studs or shank sections 35 of the tension pads T or T' as shown in FIGS. 50 and 50A, are externally threaded into the respective threaded holes 35' in the web portion 1' of the channel-shaped base frame member 1 or 1a. A base nut 46 is threadably applied to each threaded anchoring stud 45, a grip washer 46' is applied to each base nut 46, and the dividing partition is then erected by telescoping the paired stud receiving holes 45'-45' over the threaded anchoring studs 45. The base nuts 46 and associated grip washers 46' serve to space the rear face of the web portion 1' of the channel-shaped base frame member 1 or 1a of the dividing partition from the tile face Vt of the vertical room wall V for a distance in the order of two or three inches.

When the base end of the dividing partition has been vertically and laterally leveled by external manipulation of the tension pads T or T', the base nuts 46 and lock nuts 48 may be re-adjusted as required to rigidly clamp the web portion 1' of the channel-shaped base frame member 1 or 1a of the dividing partition between the grip washer 46' and the lock washer 47; thereby precisely leveling and rigidly anchoring each dividing partition to the vertical room wall, with the center lines of the dividing partition units S or dividing partition parts S' in precise parallelism.

Anchoring means A''' constructed as shown in FIGS. 51 and 51A may also be used to support the base end of each dividing partition in cantilever suspension from the vertical room wall V. The anchoring means A''' comprise a series of paired expansion shields 57 which are insertable into closed end holes formed in the vertical wall V. A bonding cement or adhesive such as epoxy resin may be injected into the closed end holes formed in the wall V before the expansion shields 57 are inserted. A threaded anchor rod 58 is threadably inserted into each expansion shield 57. The expansion shield 57 is so constructed as to cause the inner end thereof to laterally expand into truncated form when the threaded anchor rod 58 is then applied thereto. A coating of bonding cement or adhesive 43' such as epoxy resin is applied to the exposed face of the wall V or facing tile Vt to bond the frontal plate 42 thereto. The frontal plate 41 is further securely anchored by the clamp nuts 44 applied to the anchor rods 58 which extend through the frontal plate 42. A series of threaded studs 45 may form a continuation of the wing bolts 55 as shown in FIGS. 51 and 51A, or may alternatively be rigidly welded or otherwise secured to the frontal plate 42, and extend forwardly from the frontal plate 42 and through the vertically elongated holes 45' formed in the web portion 1' of the channel-shaped base frame member 1 or 1a.

Before the dividing partition S or dividing partition part S' is mounted on the vertical room wall V, the threaded shank 35 of the tension pads T or T' as shown in FIGS. 51 and 51A, are externally threaded in the respective threaded holes 35' of the channel-shaped base frame member 1 or 1a. A base nut 46 is threadably applied to each threaded anchoring stud 45, a grip washer 46' is applied to each base nut 46, and the dividing partition is then erected by telescoping the paired stud receiving holes 45'-45' over the threaded anchoring studs 45. The base nuts 46 and associated grip washers 46' serve to space the rear face of the web portion 1' of the channel-shaped base frame member 1 or 1a of the dividing partition from the tile face Vt of the vertical room wall V for a distance in the order of two or three inches. A lock washer 47 and a lock nut 48 are then applied to that part of the respective threaded studs 45 which project within the channel-shaped base frame 1 or 1a of the dividing partition.

When the base end of the dividing partition has been vertically and laterally leveled by external manipulation of the tension pads T or T', the base nuts 46 and lock nuts 48 may be readjusted as required to rigidly clamp the web portion 1' of the channel-shaped base frame member 1 or 1a of the dividing partition between the grip washer 46'

and the lock washer 47; thereby precisely leveling and rigidly anchoring each dividing partition to the vertical room wall, with the center lines of the dividing partition units S or dividing partition parts S' in precise parallelism.

When the base ends of all of the dividing partition units S or dividing partition parts S' have been rigidly anchored to the vertical room wall V as by the anchoring means A, A', A'' or A''' above described, and also leveled by the adjustable leveling and tensioning pads T or T' above described, so that all of the dividing partitions of the cubicle assemblies are rigidly anchored and in precise parallelism, the gap space between the base end of each dividing partition and the tiled face Vt' of the vertical room wall V may be covered and concealed by removable wall filler strips F.

The wall filler strips F as shown in FIGS. 1, 2, 3, 4, 10 and 11 may comprise a pair of complementary side wall plates 60 which are of sufficient width to conceal the rectangular holes 48' formed at the rear vertical end of the side wall-facing sections 2a of the side wall panels 2-2 or 2'-2', when the rear vertical end of the plates 60 abut the facing tile Vt. The upper and lower ends of each side plate 60 may present inturned lips which snugly overlap the exposed portions of the inturned flanges 2c of the side wall-facing sections 2a. The front ends of each side plate 60 may present a return bend portion 60' designed to engage two or more hook clips 61 welded or bonded to the side wall-facing sections 2a adjacent the rectangular holes 48' therein. The rear end of each side plate 60 may be removably secured as by screws 65 to one or more angle clips 62 secured to the adjacent end of the frontal plate 42. The space between the rear ends of the upper and lower cap members 6 or 6' and the facing tile Vt, is concealed by complementary upper and lower cap plates 64 of corresponding shape, with each cap plate 64 particularly overlapping the rear ends of the cap members 6 or 6' with which it is associated. Each cap plate 64 presents inturned lips along the side edges thereof which overlap the adjacent inturned lips of the complementary side plates 60-60.

The space between the rear end of the upper and lower cap members 6 or 6' and the vertical room wall, may be covered and concealed by cap plates 64 having a facing section conforming in shape to the cap members 6 or 6'. Each of the cap plates 64 presents inturned lips along the side edges thereof which interfit with the inturned lips presented by the upper and lower ends of the side plates 60. The side plates 60 are removable and replaceable should it be desired to adjust the leveling or tension pads T or T' on the anchoring means A, A', A'' or A'''.

The wall filler strips F, shown in FIGS. 30, 32 and 34, may comprise a pair of complementary flat side plates 60a of sufficient width to overlap and cover the rectangular holes 48' in the side wall-facing sections 2a of the dividing partition, when the rear vertical edges of the side plates 60a-60a abut against the facing tile Vt. Each flat side plate 60a preferably presents inturned lips at the upper and lower ends thereof which snugly overlap the exposed portions of the horizontally extending inturned flanges 2c of the side wall-facing sections 2a of the dividing partition. The flat side plates 60a-60a may be suitably secured in position for convenient removal by screws 65 threaded into the side wall-facing panels 2a, or alternatively, by screws threaded into angle clips 62 fixed to the adjacent ends of the frontal plate 42 as shown in FIGS. 10 and 11. The wall filler strips F shown in FIGS. 30, 32 and 34 also include complementary upper and lower cap plates 64 applied to the rear ends of the upper and lower cap members 6 or 6' of the dividing partition. Each cap member 64 may present a V-shaped facing section conforming in shape to the inclined facing sections 6b-6b of the cap member 6 as shown in FIGS. 30, 32 and 33; or the cap member 64 may present a flat facing section conforming to the flat facing section 6c of the associated

cap member 6'. The side edges of each cap member 64 terminate in inturned lips which overlap the adjacent inturned lips presented by the upper and lower ends of the flat side plates 60a. Since flat side plates 60a are removably secured as by screws 65 to the side wall-facing sections 2a and 2a of the dividing partition, adjustments of the leveling and tension pads T or T' and the anchoring means A, A', A'' or A''' can be made as desired.

The wall filler strips F shown in FIGS. 41, 42 and 46 comprise a pair of complementary filler plates, each presenting a straight side wall section 60a designed to snugly overlap the rear end of the side wall-facing section 2a of the dividing partition, and an inclined cap section 60b at each end thereof which is designed to snugly overlap the rear ends of the upper and lower inclined cap-forming portions 2c'' extending from the upper and lower ends of the side wall section 2a of the dividing partition. One of the inclined cap sections 60b terminates in an inturned lip 60b' designed to snugly abut the side of the adjacent semi-tubular cap member 6'' of the dividing partition, and the opposite cap section 60b terminates in a curvilinear section 60c designed to overlap and grip the rear end of the opposite semi-tubular cap member 6'' of the dividing partition. The complementary filler plates made as above described, are telescopically applied in reversed position to the base end of the dividing partition as shown in FIG. 42, to fully enclose the space between the base end of the dividing partition and the facing tile Vt of the room wall. The complementary filler plates may be removably secured to the base end of the dividing partition as by screws 65.

It will be appreciated that a pair of complementary filler strips F, similar to the filler strips F shown in FIGS. 41, 42 and 45 and above described, may be applied when appropriately modified, to surround the base end of the dividing partition construction shown in FIGS. 23 and 26. Such modified filler strips would each present a wall-facing section 60a designed to overlap and conceal the rectangular openings 48' formed in the rear end of the side wall-facing section 2a of the construction shown in FIGS. 23 and 26, the upper and lower cap sections 60b would extend normal to the vertical facing section 60a and designed to snugly overlap the upper and lower wedge-shaped flanges 2c'-2c' extending inwardly from the upper and lower ends of the side wall-facing section 2a of this partition construction. One of the inturned cap sections 60b of each modified filler plate would be applied to abut against the side of one of the semi-tubular cap members 6'' of the partition, and the opposite inturned cap section 60b would terminate in a crown formation 60c shaped to snugly overlap and grip the inner end of the opposite semi-tubular cap member 6'' of this dividing partition. When these modified filler plates are reversibly applied to the base end of the dividing partition construction shown in FIGS. 23 and 26, the space between the base end thereof and the tile facing Vt will be fully concealed, and the complementary filler plates can be removably secured to the side wall-facing sections 2a-2a of the partition construction shown in FIGS. 23 and 24 as by spaced screws 65.

In the event the cubicle installation is to be placed in the corner of a room as shown in FIGS. 1-2 and 30-31, the vertical room wall which extends at an angle to the room wall V on which the base sections of the dividing partition or partitions are mounted in cantilever suspension, may provide one wall of a corner cubicle or compartment. To form such corner cubicle or compartment, a wall panel or pilaster P'' is secured as by saddle brackets 29 to the room wall which forms one side of the corner compartment. The wall panel or pilaster P'' may have the same length and structural features as the pilaster unit P heretofore described. The wall panel or pilaster P'' must be mounted in precise alignment with the pilaster units P or pilaster parts P'' associated with the dividing partition units S or dividing partition parts S' whose base ends

are rigidly mounted and supported by the vertical room wall V. Also, the wall panel or pilaster P" should be of such width as to define a precisely dimensioned door opening between its outer vertical jamb edge and the corresponding jamb edge of the adjacent pilaster unit P or pilaster part P'.

The wall panel or pilaster P" may have a door stop 24 constructed as heretofore described, mounted on its vertical jamb edge, or may have upper and lower hinge brackets 21 and 23 constructed as heretofore described, mounted on its jamb edge as shown in FIGS. 1 and 30. The wall brackets 29 may be similar in construction to the saddle brackets 15 used to secure the partition unit P to the front end of the dividing partition unit S as heretofore described and shown in FIGS. 2, 3, 4, and 11. Where the wall panel or pilaster P" is to support a door D, the saddle brackets 29 attached thereto should be securely anchored to the adjacent room wall, as by bolts which are threaded into expansion shields embedded in the adjacent room wall.

From the above disclosure, it is apparent that the dividing partition units S or dividing partition parts S' which are to form the cubicle installation, may selectively contain internal reinforcing framework as shown in FIGS. 3 and 33, or internal reinforcing framework as shown in FIG. 14, or internal reinforcing framework as shown in FIGS. 42 and 43, as will best meet the architect's specification and withstand the use and abuse to which the installation may be subjected during a lifetime of use and abuse. The engineered strength and ability to support heavy cantilever loads of the vertical room wall V to be erected, or the strength and ability to support cantilever loads of the pre-erected room wall V, should also be taken into account in selecting the anchoring means A, A', A" or A''' above described which will best rigidly secure the base end of the dividing partition unit S or dividing partition part S' to the room wall without downsag or sidesway thereof during years of use and abuse.

The dividing partition units S or dividing partition parts S' which are to form the cubicle installation, may also be selectively provided with horizontally extending cap members 6 which are V-shaped in transverse section, or horizontally extending cap members 6' which present relatively flat facing sections 6c, or semi-tubular cap members 6" associated with relatively flat wedge-shaped inturned flanges 2c' presented by the side wall-facing sections 2a-2a of the side panels 2-2 or 2'-2', or associated with complementary inturned flanges 2c''' extending from inclined cap sections 2c'' of the side wall-facing panels 2a-2a; as selected by the architect or building owner for architectural appearance and strength.

From the above disclosure, it will be appreciated that the various components of the dividing partition units S or dividing partition parts S', as well as the pilaster units P or pilaster parts P', may be interchangeably adapted and used within the purview of this invention as selectively desired.

While certain novel features of this invention have been disclosed herein and are pointed out in the claims, it will be understood that various omissions, substitutions, and changes may be made by those skilled in the art without departing from the spirit of this invention.

What is claimed is:

1. A dividing partition and front wall forming pilaster unit designed to be secured in cantilever suspension from a room wall and in spaced relation to the room floor and ceiling which includes; a vertical base frame member designed to be rigidly secured to a vertical room wall; a pair of spaced wall forming panels together presenting vertically extending inturned flange portions overlapping and secured to the rear face of said base frame member, a pair of dividing partition forming side panel sections tapering forwardly from said base frame member, a pair of transversely aligned and laterally flared flange sections extending from the front vertical ends of said partition

forming side panel sections and together forming the rear wall of the front wall forming pilaster, and outturned flange portions extending forwardly from the vertical and horizontal ends of said rear wall forming flange sections; a front wall facing pan presenting a front panel section forming the front wall of the pilaster, and inturned flange portions extending rearwardly from the vertical and horizontal ends of said front panel section which are respectively secured to the corresponding outturned flange portions of said rear wall forming flange sections; and horizontally extending upper and lower cap members secured to the horizontal upper and lower ends of said side panel sections of the dividing partition.

2. A dividing partition and front wall forming pilaster unit designed to be secured in cantilever suspension from a room wall and in spaced relation to the room floor and ceiling which includes; a vertical base frame member designed to be rigidly secured to a vertical room wall; a pair of spaced wall forming panels together presenting vertically extending inturned flange portions overlapping and secured to the rear face of said base frame member, a pair of dividing partition forming side panel sections tapering forwardly from said base frame member, a pair of transversely aligned and laterally flared flange sections extending from the front vertical ends of said partition forming side panel sections and together forming the rear wall of the front wall forming pilaster, and outturned flange portions extending forwardly from the vertical and horizontal ends of said rear wall forming flange sections; a front wall facing pan presenting a front panel section forming the front wall of the pilaster, and inturned flange portions extending rearwardly from the vertical and horizontal ends of said front panel section which are respectively secured to the corresponding outturned flange portions of said rear wall forming flange sections; and horizontally extending upper and lower cap member secured to the horizontal upper and lower ends of said side panel sections of the dividing partition; reinforcing liners bonded to the inner faces of the side panel sections of the dividing partition, and spaced wedge-shaped reinforcing members extending forwardly from the inner face of said base frame member and bonded to said reinforcing liners.

3. A dividing partition and front wall forming pilaster unit designed to be secured in cantilever suspension from a room wall and in spaced relation to the room floor and ceiling which includes; a vertical base frame member of channel shaped cross-section whose web portion is designed to be rigidly secured to a vertical room wall; a pair of spaced wall forming panels together presenting vertically extending inturned flange portions overlapping and secured to the rear face of the web portion of said channel shaped base frame member, a pair of dividing partition forming side panel sections tapering forwardly from said channel shaped base frame member, a pair of transversely aligned and laterally flared flange sections extending from the front vertical ends of said partition forming side panel sections and together forming the rear wall of the front wall forming pilaster, and outturned flange portions extending forwardly from the vertical and horizontal ends of said rear wall forming flange sections which respectively terminate in outflared lip portions; a front wall facing pan presenting a front panel section forming the front wall of the pilaster, inturned flange portions extending rearwardly from the vertical and horizontal ends of said front panel section and respectively terminating in outflared lip portions positioned in adjacent matching relation to the respective outflared lip portions of said rear wall forming flange sections, and vertically and horizontally extending semi-tubular edging strips presenting inturned lip portions interlocked to the adjacently paired outflared lip portions extending along the vertical and horizontal ends of said front wall facing pan and said rear wall forming flange sections to thereby provide a front wall forming pilaster; horizontal

ly extending upper and lower cap members secured to the horizontal upper and lower ends of said side panel sections of the dividing partition; reinforcing liners bonded to the inner faces of the side panel sections of the dividing partition, and spaced wedge-shaped reinforcing members extending forwardly from the inner face of the web portion of said channel shaped base frame member and bonded to said reinforcing liners.

4. A dividing partition and front wall forming pilaster unit designed to be secured in cantilever suspension from a room wall and in spaced relation to the room floor and ceiling which includes; a vertical base frame member of channel shaped cross-section whose web portion is designed to be rigidly secured to a vertical room wall; a pair of spaced wall forming panels together presenting vertically extending inturned flange portions overlapping and secured to the rear face of the web portion of said channel shaped base frame member, a pair of dividing partition forming side panel sections tapering forwardly from said channel shaped base frame member, a pair of upper and lower flange portions extending inwardly from the upper and lower ends of said partition forming side panel sections and respectively terminating in paired outwardly flared lip portions, a pair of transversely aligned and laterally flared flange sections extending from the front vertical ends of said partition forming side panel sections and together forming the rear wall of the front wall forming pilaster, and outturned flange portions extending forwardly from the vertical and horizontal ends of said rear wall forming flange sections which respectively terminate in outflared lip portions; a front wall facing pan presenting a front panel section forming the front wall of the pilaster, inturned flange portions extending rearwardly from the vertical and horizontal ends of said front panel section and respectively terminating in outflared lip portions positioned in adjacent matching relation to the respective outflared lip portions of said rear wall forming flange sections, and vertically and horizontally extending semi-tubular edging strips presenting inturned lip portions interlocked to the adjacently paired outflared lip portions extending along the vertical and horizontal ends of said front wall facing pan and said rear wall forming flange sections to thereby provide a front wall forming pilaster; horizontally extending upper and lower cap members each presented inturned lip portions interlocked to the paired outflared lip portions extending along the horizontal upper and lower ends of said side panel sections of the dividing partition with the front end of each of said cap members coped and welded to the adjacent horizontal edging strip of the front wall forming pilaster; reinforcing liners bonded to the inner faces of the side panel sections of the dividing partition, and spaced wedge-shaped reinforcing members extending forwardly from the inner face of the web portion of said channel shaped base frame member and bonded to said reinforcing liners.

5. A dividing partition and front wall forming pilaster unit designed to be secured in cantilever suspension from a room wall and in spaced relation to the room floor and ceiling which includes; a generally U-shaped base frame comprising a vertically extending base frame member of generally channel shaped cross-section whose web portion is designed to be rigidly secured to a vertical room wall, and upper and lower horizontally extending arms of generally channel shaped cross-section respectively secured at one end thereof to the upper and lower ends of said channel-shaped base frame member; a pair of spaced wall forming panels together presenting vertically extending inturned flange portions overlapping and secured to the rear face of the web portion of said channel shaped base frame member, a pair of dividing partition forming side panel sections tapering forwardly from said channel shaped base frame member, a pair of upper and lower flange portions extending inwardly from the upper and lower ends of said partition forming side panel sec-

tions and overlapping the adjacent upper and lower arms of said U-shaped base frame, a pair of transversely aligned and laterally flared flange sections extending from the front vertical ends of said partition forming side panel sections and together forming the rear wall of the front wall forming pilaster, and outturned flange portions extending forwardly from the vertical and horizontal ends of said rear wall forming flange sections; a front wall facing pan presenting a front panel section forming the front wall of the pilaster, and inturned flange portions extending rearwardly from the vertical and horizontal ends of said front panel section which are respectively secured to the corresponding outturned flange portions of said rear wall forming flange sections; and horizontally extending upper and lower cap members secured to the adjacently paired upper and lower inturned flange portions of said side panel sections of the dividing partition.

6. The dividing partition and front wall forming pilaster unit designed to be secured in cantilever suspension from a room wall and in spaced relation to the room floor and ceiling which includes; a generally U-shaped base frame comprising a vertically extending base frame member of generally channel shaped cross-section whose web portion is designed to be rigidly secured to a vertical room wall, and upper and lower horizontally extending arms of generally channel shaped cross-section respectively secured at one end thereof to the upper and lower ends of said channel-shaped base frame member; a pair of spaced wall forming panels together presenting vertically extending inturned flange portions overlapping and secured to the rear face of the web portion of said channel shaped base frame member, a pair of dividing partition forming side panel sections tapering forwardly from said channel-shaped base frame member, a pair of upper and lower flange portions extending inwardly from the upper and lower ends of said partition forming side panel sections and overlapping the adjacent upper and lower arms of said U-shaped base frame, and with said upper and lower flange portions respectively terminating in paired upper and lower outwardly flared lip portions, a pair of transversely aligned and laterally flared flange sections extending from the front vertical ends of said partition forming side panel sections and together forming the rear wall of the front wall forming pilaster, and outturned flange portions extending forwardly from the vertical and horizontal ends of said rear wall forming flange sections; a front wall facing pan presenting a front panel section forming the front wall of the pilaster, and inturned flange portions extending rearwardly from the vertical and horizontal ends of said front panel section which are respectively secured to the corresponding outturned flange portions of said rear wall forming flange section; horizontally extending upper and lower cap members each presenting inturned lip portions interlocked to the paired outflared lip portions associated with said horizontal upper and lower inturned flange portions of said side panel sections of the dividing partition; reinforcing liners bonded to the inner faces of the side panel sections of the dividing partition, and spaced wedge-shaped reinforcing members extending forwardly from the inner face of the web portion of said channel shaped base frame member and bonded to said reinforcing liners.

7. A dividing partition and front wall forming pilaster unit designed to be secured in cantilever suspension from a room wall and in spaced relation to the room floor and ceiling which includes; a generally U-shaped base frame comprising a vertically extending base frame member of generally channel shaped cross-section whose web portion is designed to be rigidly secured to a vertical room wall, and upper and lower horizontally extending arms of generally channel shaped cross-section respectively secured at one end thereof to the upper and lower ends of said channel-shaped base frame member; a pair of spaced wall forming panels together presenting vertically extending inturned flange portions overlapping and secured

to the rear face of the web portion of said channel shaped base frame member, a pair of dividing partition forming side panel sections tapering forwardly from said channel shaped base frame member, a pair of upper and lower flange portions extending inwardly from the upper and lower ends of said partition forming side panel sections and overlapping the adjacent upper and lower arms of said U-shaped base frame and with said upper and lower flange portions respectively terminating in paired upper and lower outwardly flared lip portions; a pair of transversely aligned and laterally flared flange sections extending from the front vertical ends of said partition forming side panel sections and together forming the rear wall of the front wall forming pilaster, and outturned flange portions extending forwardly from the vertical and horizontal ends of said rear wall forming flange sections which respectively terminate in outflared lip portions; a front wall facing pan presenting a front panel section forming the front wall of the pilaster, inturned flange portions extending rearwardly from the vertical and horizontal ends of said front panel section and respectively terminating in outflared lip portions positioned in adjacent matching relation to the outflared lip portions associated with the outturned flange portions of said rear wall forming flange sections, and vertically and horizontally extending semi-tubular edging strips presenting inturned lip portions respectively interlocked to the adjacently paired outflared lip portions extending along the vertical and horizontal ends of said front wall facing pan and said rear wall forming flange sections to thereby provide a front wall forming pilaster; horizontally extending upper and lower cap members each presenting inturned lip portions interlocked to the paired outflared lip portions extending from the horizontal upper and lower flange portions of said side panel sections with the front ends of each cap member coped and welded to the adjacent horizontal edging strip of the front wall forming pilaster; reinforcing liners bonded to the inner faces of the side panel sections of the dividing partition, and spaced wedge-shaped reinforcing members extending forwardly from the inner face of the web portion of said channel shaped base frame member and bonded to said reinforcing liners.

8. A cubicle assembly designed for cantilever suspension from a vertical room wall and in spaced relation to the room floor and ceiling, including in combination; a dividing partition generally wedge-shaped in horizontal section, means for rigidly securing the base end of said dividing partition in spaced relation to and in cantilever suspension from a vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member, side facing panels secured to said vertical base frame member and tapering forwardly therefrom, internal reinforcing members extending between the inner surfaces of said facing panels, and upper and lower cap members secured to the upper and lower horizontal ends of said facing panels; said securing means including a frontal member designed to be rigidly connected to the front face of the vertical room wall, a plurality of spaced studs rigidly projecting forwardly from said frontal member and through aligned holes in the vertical base frame member of the dividing partition, a leveling nut and clamp nut threadably applied to each of said studs on opposite sides of said base frame member, a series of spaced tension applying and leveling pads each presenting a head portion designed to brace against said frontal members and threaded stem section threadably connected to said base frame member, and spaced access openings along the rear vertical edge of said side facing panels through which a clamp nut manipulating tool may be inserted.

9. A cubicle assembly designed for cantilever suspension from a vertical room wall and in spaced relation to the room floor and ceiling, including in combination; a dividing partition generally wedge-shaped in horizontal section, means for rigidly securing the base end of said dividing partition in spaced relation to and in cantilever suspension from a vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member designed to be secured in spaced relation to a vertical building wall, side facing panels secured to said vertical base frame member and tapering forwardly therefrom, reinforcing liners bonded to the inner surfaces of said facing panels, a series of spaced reinforcing members of wedge-shaped form bonded to said reinforcing liners and extending horizontally from said vertical base frame member and terminating substantially adjacent the front end of said facing panels, and upper and lower capping members interlocked to the upper and lower horizontal ends of said facing panels; said securing means including a frontal member rigidly connected to the front face of the vertical room wall, a plurality of spaced studs rigidly projecting forwardly from said frontal member and through aligned holes in the vertical base frame member of the dividing partition, a leveling nut and clamp nut threadably applied to each of said studs on opposite sides of said base frame member, a series of spaced tension applying and leveling pads each presenting a head portion designed to brace against said frontal member and a threaded stem section threadably secured to said base frame member, and spaced access openings along the rear vertical edge of at least one of said side facing panels through which a clamp nut manipulating tool may be inserted.

10. A cubicle assembly designed for cantilever suspension from a vertical room wall and in spaced relation to the room floor and ceiling, including in combination; a dividing partition generally wedge-shaped in horizontal section designed to extend laterally from and substantially normal to the vertical room wall, means for rigidly securing the base end of said dividing partition in spaced relation to and in cantilever suspension from a vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member designed to be secured in spaced relation to a vertical building wall, side facing panels secured to said vertical base frame member and tapering forwardly therefrom, reinforcing liners bonded to the inner surfaces of said facing panels, a series of spaced reinforcing members of wedge-shaped form bonded to said reinforcing liners and extending horizontally from said vertical base frame member and terminating substantially adjacent the front end of said facing panels, and upper and lower cap members interlocked to the upper and lower horizontal ends of said facing panels; said securing means including a frontal member rigidly connected to the front face of the vertical room wall, a plurality of spaced studs rigidly projecting forwardly from said frontal member and through aligned holes in the vertical base frame member of the dividing partition, a leveling nut and clamp nut threadably applied to each of said studs on opposite sides of said base frame member, a series of spaced tension applying and leveling pads each presenting a head portion designed to brace against said frontal member and a threaded stem section threadably secured to said base frame member, spaced access openings along the rear vertical edge of at least one of said side facing panels through which a clamp nut manipulating tool may be

inserted, and wall filler strips secured to and extending around the base end of said dividing partition and in substantially abutting relation to the front face of the vertical room wall.

11. A cubicle assembly secured in cantilever suspension from a vertical room wall and in spaced relation to the room floor and ceiling, including in combination; a dividing partition generally wedge-shaped in horizontal section, means for rigidly securing the base end of said dividing partition in cantilever suspension from the vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member of channel-shaped cross-section whose web portion is in spaced relation to the front face of the vertical room wall, a pair of spaced side facing panels secured to said vertical base frame member and tapering forwardly therefrom, internal reinforcing members extending between the inner surfaces of said facing panels, and upper and lower cap members secured to the horizontal upper and lower ends of said facing panels; said securing means including a frontal plate secured to the front face of the vertical room wall, a plurality of spaced studs each rigidly anchored in the vertical room wall and projecting forwardly from said frontal plate and through an aligned hole in the web portion of said channel shaped base frame member of the dividing partition, a leveling nut and clamp nut threadably applied to each of said studs on opposite sides of the web portion of said base frame member, a series of spaced tension applying and leveling pads each presenting a head portion designed to brace against said frontal plate and a stem section threadably connected to the web portion of said base frame member, spaced access openings along the rear vertical edges of said side facing panels and the flange portions of said channel shaped base frame member and through which a clamp nut manipulating tool may be inserted, and wall filler strips secured to and extending around the base end of said dividing partition and in substantially abutting relation to the front face of the vertical room wall.

12. A cubicle assembly secured in cantilever suspension from a vertical room wall and in spaced relation to the room floor and ceiling, including in combination; a dividing partition generally wedge-shaped in horizontal section, means for rigidly securing the base end of said dividing partition in cantilever suspension from the vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member of channel-shaped cross-section whose web portion is in spaced relation to the front face of the vertical room wall, a pair of spaced side facing panels secured to said vertical base frame member and tapering forwardly therefrom, internal reinforcing members extending between the inner surfaces of said facing panels, and upper and lower cap members secured to the horizontal upper and lower ends of said facing panels; said securing means including a frontal plate, means for anchoring said frontal plate to the front face of the vertical room wall, a plurality of spaced studs projecting from said frontal plate and through aligned holes in the web portion of said channel shaped base frame member of the dividing partition, a leveling nut and clamp nut threadably applied to each of said studs on opposite sides of the web portion of said base frame member, a series of spaced tension applying and leveling pads each presenting a head portion designed to brace against said frontal plate and a stem section threadably connected to the web portion of said base frame member, said clamp nuts and tension pads being accessible for ex-

ternal tool manipulation through the space between said frontal plate and the web portion of said base frame member, spaced access openings along the rear vertical edges of said side facing panels and the flange portions of

5 said channel shaped base frame member and through
which a clamp nut manipulating tool may be inserted,
and wall filler strips secured to and extending around
the base end of said dividing partition and in substantially
abutting relation to the front face of the vertical room
wall.

13. A cubicle assembly secured in cantilever suspension

from a vertical room wall and in spaced relation to the room floor and ceiling, including in combination; a dividing partition generally wedge-shaped in horizontal section, means for rigidly securing the base end of said dividing partition in cantilever suspension from the vertical

room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member of

channel shaped cross-section whose web portion is in spaced relation to the front face of the vertical room wall, a pair of spaced side facing panels secured to said vertical base frame member and tapering forwardly therefrom, internal reinforcing members extending between the inner surfaces of said facing panels, and upper and lower cap members secured to the horizontal upper and

lower cap members secured to the horizontal upper and
30 lower ends of said facing panels; said securing means including a backing plate applied to the rear face of the vertical room wall and a frontal plate applied to the front face thereof, a series of spaced bolts each anchored to said backing plate and extending through the frontal plate and

35 backing plate and extending through the frontal plate and vertical room wall through an aligned hole in the web portion of said channel shaped base frame member of the dividing partition, a leveling nut and clamp nut threadably applied to each of said anchor bolts on opposite sides of the web portion of said base frame member, a series

40 of spaced tension applying and leveling pads each presenting a head portion designed to brace against said frontal plate and a stem section threadably connected to the web portion of said base frame member, said clamp nuts and tension pads being accessible for external tool manipulation through the space between said frontal plate and

45 the web portion of said base frame member, spaced access openings along the rear vertical edges of said side facing panels and the flange portions of said channel shaped base frame member and through which a clamp nut manin-

50 ulating tool may be inserted, and wall filler strips secured to and extending around the base end of said dividing partition and in substantially abutting relation to the front face of the vertical room wall.

55 14. A cubicle assembly secured in cantilever suspension from a vertical room wall and in spaced relation to the room floor and ceiling, including in combination; a dividing partition generally wedge-shaped in horizontal section, means for rigidly securing the base end of said dividing partition in cantilever suspension from the vertical

60 dividing partition in cantilever suspension from the vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said divid-

65 ing partition including a vertical base frame member of channel-shaped cross-section whose web portion is in spaced relation to the front face of the vertical room wall, a pair of spaced side facing panels secured to said vertical base frame member and tapering forwardly therefrom, internal reinforcing members extending between the

inner surfaces of said facing panels, and upper and lower cap members secured to the horizontal upper and lower ends of said facing panels; said securing means including a frontal plate applied to the front face of the vertical room wall, vertically spaced plates of angular cross-

section anchored in the vertical room wall and having spaced studs secured to each of said plates and secured to said frontal plate, a plurality of spaced studs each rigidly anchored to said frontal plate and extending through aligned holes in the web portion of said channel-shaped base frame member of the dividing partition, a leveling nut and clamp nut threadably applied to each of said studs on opposite sides of the web portion of said base frame member, a series of spaced tension applying and leveling pads each presenting a head portion designed to brace against said frontal plate and a stem section threadably connected to the web portion of said base frame member, said clamp nuts and tension pads being accessible for external tool manipulation through the space between said frontal plate and the web portion of said base frame member, spaced access openings along the rear vertical edges of said side facing panels and the flange portions of said channel shaped base frame member and through which a clamp nut manipulating tool may be inserted, and wall filler strips secured to and extending around the base end of said dividing partition and in substantially abutting relation to the front face of the vertical room wall.

15. A cubicle assembly secured in cantilever suspension from a vertical room wall and in spaced relation to the room floor and ceiling, including in combination; a dividing partition generally wedge-shaped in horizontal section, means for rigidly securing the base end of said dividing partition in spaced relation to and in cantilever suspension from the vertical room wall, a front wall forming pilaster fixed to the front end of said wedge-shaped dividing partition and having a vertical length substantially corresponding to the vertical length of said dividing partition, and a door swingably mounted on a jamb edge of said pilaster; said dividing partition including a vertical base frame member of channel-shaped cross-section whose web portion is in spaced relation to the front face of the vertical room wall, a pair of spaced side facing panels secured to said vertical base frame member and tapering forwardly therefrom, internal reinforcing members extending between the inner surfaces of said facing panels, and upper and lower cap members secured to the horizontal upper and lower ends of said facing panels; said securing means including a frontal plate bonded to the front face of the vertical room wall, a plurality of spaced bolts each extending through a bore formed in the vertical room wall and having expansible wing elements hinged thereto and insertable through said bore and laterally expansible into bracing relation against the rear face of the room wall, each of said bolts extending through said frontal plate and the web portion of said channel-shaped base frame member, a leveling nut and clamp nut threadably applied to each of said bolts on opposite sides of the web portion of said base frame member, a series of spaced tension applying and leveling pads each presenting a head portion designed to brace against said frontal plate and a stem section threadably connected to the web portion of said base frame member, said clamp nuts and tension pads being accessible for external tool manipulation through the space between said frontal plate and the web portion of said base frame member, spaced access openings along the rear vertical edges of said side facing panels and the flange portions of said channel-shaped base frame member and through which a clamp nut manipulating tool may be inserted, and wall filler strips secured to and extending around the base end of said dividing partition and in substantially abutting relation to the front face of the vertical room wall.

16. A cubicle assembly secured in cantilever suspension from a vertical room wall and in spaced relation to the room floor and ceiling, including in combination; a dividing partition generally wedge-shaped in horizontal section, means for rigidly securing the base end of said dividing partition in cantilever suspension from the vertical room wall, a front wall-forming pilaster fixed to the

front end of said wedge-shaped dividing partition and having a vertical length substantially corresponding to the vertical length of said dividing partition, and a door swingably mounted on a jamb edge of said pilaster; said dividing partition including a vertical base frame member of channel-shaped cross-section whose web portion is in spaced relation to the front face of the vertical room wall, a pair of spaced side facing panels secured to said vertical base frame member and tapering forwardly therefrom, internal reinforcing members extending between the inner surfaces of said facing panels, and upper and lower cap members secured to the horizontal upper and lower ends of said facing panels; said securing means including a frontal plate bonded to the front face of the vertical room wall, a plurality of spaced expansion shields anchored in the vertical room wall, an anchor rod threaded into each of said expansion shields and extending through said frontal plate and the web portion of said channel-shaped base frame member, a leveling nut and clamp nut threadably applied to each of said anchor rods on opposite sides of the web portion of said base frame member, a series of spaced tension applying and leveling pads each presenting a head portion designed to brace against said frontal plate and a stem section threadably connected to the web portion of said base frame member, said clamp nuts and tension pads being accessible for external tool manipulation through the space between said frontal plate and the web portion of said base frame member, spaced access openings along the rear vertical edges of said side facing panels and the flange portions of said channel-shaped base frame member and through which a clamp nut manipulating tool may be inserted, and wall filler strips secured to and extending around the base end of said dividing partition and in substantially abutting relation to the front face of the vertical room wall.

17. In a cubicle assembly, a dividing partition generally wedge-shaped in horizontal section whose base end is designed to be secured in cantilever suspension to a vertical room wall and in spaced relation to the room floor and ceiling, and a front wall forming panel fixed to the front end of said wedge-shaped dividing partition and having a vertical length substantially corresponding to the vertical length of said dividing partition, said panel including; spaced front and rear wall forming sections together presenting paired inturned flanges extending along both vertical and both horizontal edges thereof, paired outflared lips extending from said paired inturned flanges and bonded together in paired arrangement; the paired outflared lips which extend along one vertical edge of the panel being cut away to present paired upper and lower lip sections whose adjacent ends are spaced apart to define an intermediate seat formation for a hardware device, said intermediate seat formation presenting an aperture extending through the intermediate area of said paired inturned flanges, upper and lower ribs extending outwardly from said paired inturned flanges at the intermediate area thereof and from said aperture to the respective adjacent terminal ends of said upper and lower outflared lip sections, a vertically extending semi-tubular edging strip presenting inturned lips telescopically applied and interlocked to the paired outflared lips extending along the other vertical edge of the panel, vertically extending upper and lower semi-tubular edging strip sections presenting inturned lips telescopically applied and interlocked to the respective upper and lower outflared lip sections extending along the said one vertical edge of the panel, horizontally extending upper and lower semi-tubular edging strips each presenting inturned lips telescopically applied and interlocked to the paired outflared lips extending along the respective upper and lower horizontal edges of the panel, the adjacent corner forming ends of said vertical and horizontal semi-tubular edging strips being mitre matched to form finished panel corners; said vertically extending upper and lower semi-tubular edging strip sections being telescopically mov-

able to temporarily overlap said intermediate seat formation to permit telescopic application of said horizontally extending upper and lower semi-tubular edging strips and thereafter outwardly movable to expose said intermediate seat formation and thereby place the respective upper and lower ends thereof in mitre match with the adjacent ends of said horizontally extending upper and lower semi-tubular edging strips.

18. In a cubicle assembly, a vertical wall forming panel designed to be secured in cantilever suspension from a vertical room wall and in spaced relation to the room floor and ceiling, said panel including; spaced front and rear wall forming sections together presenting paired in-turned flanges extending along both vertical and both horizontal edges thereof, paired outflared lips extending from said paired in-turned flanges and bonded together in paired arrangement, the paired outflared lips which extend along one vertical edge of the panel being cut away to present paired upper and lower lip sections whose adjacent ends are spaced apart to define an intermediate seat formation for a hardware device, said intermediate seat formation presenting an aperture extending through the intermediate area of said paired in-turned flanges, upper and lower ribs extending outwardly from said paired in-turned flanges at the intermediate area thereof and from said aperture to the respective adjacent terminal ends of said upper and lower outflared lip sections, a vertically extending semi-tubular edging strip presenting in-turned lips telescopically applied and interlocked to the paired outflared lips extending along the other vertical edge of the panel, vertically extending upper and lower semi-tubular edging strip sections presenting in-turned lips telescopically applied and interlocked to the respective upper and lower outflared lip sections extending along the said one vertical edge of the panel, horizontally extending upper and lower semi-tubular edging strips each presenting in-turned lips telescopically applied and interlocked to the paired outflared lips extending along the respective upper and lower horizontal edges of the panel, the adjacent corner forming ends of said vertical and horizontal semi-tubular edging strips being mitre matched to form finished panel corners; said vertically extending upper and lower semi-tubular edging strip sections being telescopically movable to temporarily overlap said intermediate seat formation to permit telescopic application of said horizontally extending upper and lower semi-tubular edging strips and thereafter outwardly movable to expose said intermediate seat formation and thereby place the respective upper and lower ends thereof in mitre match with the adjacent ends of said horizontally extending upper and lower semi-tubular edging strips.

19. In a cubicle assembly, a vertical wall forming panel designed to be secured in cantilever suspension from a vertical room wall and in spaced relation to the room floor and ceiling, and a hardware device secured to an edge of said panel intermediate the ends thereof; said panel including, spaced wall forming sections together presenting paired in-turned flanges extending along the perimetal edges thereof, spaced outflared lip sections extending from a pair of adjacent in-turned flanges and bonded together in paired arrangement, the adjacent terminal ends of said paired lip sections defining an intermediate seat formation for a hardware device, said intermediate seat formation presenting an aperture extending through the intermediate seat forming area of said paired in-turned flanges, spaced ribs extending outwardly from said paired in-turned flanges at the intermediate seat forming area thereof and from said aperture to the respective adjacent terminal ends of said flared lip sections, and spaced semi-tubular edging strips presenting in-turned lips telescopically applied and interlocked to the spaced outflared lip sections and whose adjacent terminal ends expose said intermediate seat formation; said hardware device including a saddle part having a base section seat-

ing against the outer face of said paired in-turned flanges at the seat forming area thereof and having grooves therein which receive said spaced ribs, a lip portion extending from the opposite ends of said base section and snugly overlapping the adjacent terminal ends of said semi-tubular edging strip sections, a boss portion extending from the rear face of said base section and through the aperture formed in said in-turned flanges, a clamp member presenting end rim portions designed to seat against the inner faces of said paired in-turned flanges, and an externally manipulated clamp bolt extending through said boss portion and threadably connected to said clamp member.

20. In a cubicle assembly, a vertical wall forming panel designed to be secured in cantilever suspension from a vertical room wall and in spaced relation to the room floor and ceiling, and a hardware device secured to a vertical edge of said panel intermediate the ends thereof, said panel including, spaced front and rear wall forming sections together presenting paired in-turned flanges extending along both vertical and both horizontal edges thereof, paired outflared lips extending from said paired in-turned flanges and bonded together in paired arrangement, the paired outflared lips which extend along one vertical edge of the panel being cut away to present paired upper and lower lip sections whose adjacent ends are spaced apart to define an intermediate seat formation, said intermediate seat formation presenting an aperture extending through the seat forming area of said paired in-turned flanges, upper and lower ribs extending outwardly from said paired in-turned flanges at the seat forming area thereof and from said aperture to the respective adjacent terminal ends of said upper and lower outflared lip sections, a vertically extending semi-tubular edging strip presenting in-turned lips telescopically applied and interlocked to the paired outflared lips extending along the other vertical edge of the panel, vertically extending upper and lower semi-tubular edging strip sections presenting in-turned lips telescopically applied and interlocked to the respective upper and lower outflared lip sections extending along the said one vertical edge of the panel, and horizontally extending upper and lower semi-tubular edging strips each presenting in-turned lips telescopically applied and interlocked to the paired outflared lips extending along the respective upper and lower horizontal edges of the panel, the adjacent corner forming ends of said vertical and horizontal semi-tubular edging strips being mitre matched to form finished panel corners; said hardware device including a saddle part having a base section seating against the outer face of said paired in-turned flanges at the seat forming area thereof and having grooves therein which receive said upper and lower ribs, a lip portion extending from the opposite ends of said base section and snugly overlapping the adjacent terminal ends of said semi-tubular edging strip sections, a boss portion extending from the rear face of said base section and through the aperture formed in said in-turned flanges, a clamp member presenting end rim portions designed to seat against the inner faces of said paired in-turned flanges, and an externally manipulated clamp bolt extending through said boss portion and threadably connected to said clamp member.

21. In a dividing partition of the type to be supported in cantilever arrangement from a vertical wall wherein the partition has, at least, a back vertical edge defined by a support plate and means for securing said back edge of said partition onto said wall, the improvement comprising: said securing means including a frontal plate; means for anchoring said frontal plate in a vertical position on said wall; a plurality of spaced studs projecting from said frontal plate and through aligned holes in said support plate; a leveling nut and clamp nut threadably applied to each of said studs on opposite sides of said support plate, a series of spaced tension applying and leveling pads each presenting a head portion designed to brace against said

frontal plate and a stem section threadably connected to said support plate, said leveling nuts and tension pads being accessible for external tool manipulation through the space between said frontal plate and said support plate; said support plate having flanges extending in parallel relationship away from said wall; and spaced access openings along said flanges through which a clamp nut manipulating tool may be inserted.

22. In a dividing partition of the type to be supported in cantilever arrangement from a vertical wall wherein the partition has, at least, a pair of vertically extending spaced side wall forming members joined at their back vertical edges by a vertically extending support plate and means for securing said partition onto said wall, the improvement comprising: said securing means including a frontal plate; means for anchoring said frontal plate in a vertical position on said wall; a plurality of spaced studs projecting from said frontal plate and through aligned holes in said support plate; a leveling nut and clamp nut threadably applied to each of said studs on opposite sides of said support plate, a series of spaced tension applying and leveling pads each presenting a head portion designed to brace against said frontal plate and a stem section threadably connected to said support plate, said leveling nuts and tension pads being accessible for external tool manipulation through the space between said frontal plate and said support plate; and, spaced access openings in said side walls through which a clamp nut manipulating tool may be inserted.

23. The improvement as defined in claim 22 wherein

10

15

20

25

30

said tension members are arranged in pairs with at least three pairs of said tension members being spaced along said support plate.

24. The improvement as defined in claim 22 wherein at least three of said compression members are spaced along said support plate.

25. The improvement as defined in claim 22 wherein said compression members are positioned adjacent said tension members to provide a rigid support at the tension members.
